PHONOGRAPH

Clemma R. Raney, Riverside, Ill.

Application July 24, 1928, Serial No. 295,017

157 Claims.

(Cl. 274—10)

My invention relates to phonographs.

It has among its objects to provide an improved phonograph, and more particularly to provide an improved phonograph of the type adapted to effect automatic reproduction of a series of records. Another object of my invention is to provide improved and simplified mechanism of the type indicated, wherein the flexibility of the mechanism is increased and the same also rendered more convenient in the hands of an operator, especially as regards record insertion and changes in the records in the magazine. A further object of my invention is to provide such a phonograph adapted to play records of different sizes without adjustment on the part of the operator, and, more particularly, to provide such a machine which will either play records of different size as they are fed separately or when they are mixed in the machine, and which will automatically adjust itself to the size of the record fed. Further objects of my invention are to provide improved control mechanism for placing the reproducer on the edge of a record, and if desired, upon the edges of records of different size, automatically and without adjustment on the part of the operator; an improved magazine adapted to handle records of different size separately or mixed together and adapted to permit very convenient insertion or changing of the records and to supply them to the table in a new and advantageous way while the table is rotating; improved record discharging mechanism associated with the other mechanism in an improved manner and operative to discharge a record from the table regardless of its size; improved automatic controlling mechanism operatively connecting or associated with the mechanism above mentioned for effecting an improved coordination between the mechanisms for rotating, reproducing, and discharging the reproduced record, and presenting a new record for reproduction, involving a new timing of the operations of the same, whereby the time required to begin the playing of a new record, following the completion of a record being reproduced, is materially reduced and the operation of the reproducing or feeding mechanisms, and herein both, is coordinated in a new manner with the discharge mechanism so as to perform a complete cycle of automatic operation while the discharge mechanism is operating; as well as improved and more convenient manually or automatically adjustable control or setting mechanism associated with the mechanism in an improved manner and whereby improved setting is obtainable. These and other

objects and advantages of my improved construction will, however, hereinafter more fully appear.

In the accompanying drawings, I have shown for purposes of illustration, one embodiment 5 which my invention may assume in practice.

In these drawings,—

Fig. 1 is a plan view of this embodiment of my invention, certain of the parts being broken away to facilitate illustration;

Fig. 2 is a longitudinal sectional view of the mechanism shown in Fig. 1;

Fig. 3 is a sectional view on line 3—3 of Fig. 1, the switch being omitted to facilitate illustration;

Fig. 4 is a sectional view on line 4—4 of Fig. 3;

Fig. 5 is an enlarged sectional detail of the record delivery mechanism and table shown in Fig. 2, the record being shown in process of delivery to the table;

Fig. 6 is a detail elevation of the record discharging mechanism showing the same acting upon a record on the table;

Fig. 7 is an enlarged detail view of the magazine showing records therein;

Fig. 8 is a detail sectional view on line 8—8 of Fig. 7;

Fig. 9 is a side elevation of the drive connections between the drum and magazine shafts showing the eccentric sprocket and chain tightener connection, and

Fig. 10 is a plan view of the drum surface shown as a plane surface.

In this illustrative construction, I have disclosed a power driven mechanism operative from 35 a motor 1 and including a rotating record table 2 driven by the motor and a tone or sound arm 3 carrying a reproducer 4 adapted to cooperate with a record on the table 2, improved means being provided herein whereby the tone arm is controlled and records are supplied to and discharged from the table while the latter rotates and in timed relation to the movements of the tone arm, all in a manner especially adapted to use in connection with records of different size and subject 40 to the control of improved controlling mechanism, as will hereinafter more fully appear.

Referring first to the general arrangement of this illustrative construction in order to locate the several mechanisms to be hereinafter described, it will be noted that the table 2 is disposed directly above the motor 1 (Fig. 2). Further, the reproducer mechanism is adapted to swing laterally above the table and relative to a record on the table in a well known manner (Figs. 55

1 and 2). Improved reproducer controlling mechanism, herein including a drum, is disposed below the table (Fig. 2) and above the motor 1. Moreover, cooperating record feeding mechanism, 5 herein including a laterally feeding conveyor mechanism, is disposed to the left of the table (Figs. 1, 2) and adapted to feed a record thereon. Also, improved record discharging mechanism is herein disposed below the table and adapted to 10 discharge a record to a chute at the right. Improved manually adjustable controlling and setting mechanism, including an adjustable pointer movable relative to a switch and a series of numerals, is also shown in the lower left-hand corner of Fig. 1.

Considering more specifically the drive arrangement of the mechanism shown, it will be noted that the motor 1, which is preferably an electric motor, has a vertical shaft 5. Herein, 20 this shaft 5 extends upward a substantial distance and through a horizontal sheet metal base 6 forming what may be called the floor of the mechanism below the table 2. As shown, this base 6 is carried on a horizontal main casting 7 suitably supported on the frame above the motor, and is also provided with downwardly folded edges 8 removably supported on suitable supports 9 on a usual cabinet 10, thereby permitting ready 25 access to the parts. See Fig. 2. As illustrated, 30 the table 2 is herein fixed to the upper end of the shaft 5 and rotatable on a fixed vertical axis in fixed horizontal planes throughout the operation of the phonograph, while the power drive for the whole mechanism is preferably taken off of this shaft 5 at a point between the motor and the base 6.

Referring next to the mechanisms driven by this shaft, we will first consider the reproducer controlling mechanism. As shown, a worm 11 40 on the shaft 5 meshes with a worm gear 12. This gear 12 is rotatable on a transverse horizontal axis and is supported by suitable bearings 13 and 14 on the main casting 7, a shaft 15 extending through the worm gear 12 and being supported in these bearings. Herein the gear 12 is provided with an elongated sleeve 16 extending toward the bearing 14. This sleeve carries on its end toward that bearing a driving dog ratchet 17 of usual form and normally rotatable with the gear 12 relative to the shaft 15. Herein, the sleeve 16 is also adapted to be connected to the shaft 15 when desired by means of a spring 45 pressed driving dog connection 18 which is pivotally supported at 19 on the adjacent end of a rotatable drum 20 secured to shaft 15, and is therefore rotatable with said drum. As shown, this dog connection 18 is constantly biased into engagement with ratchet 17 by its spring and has a roller at its free end adapted to engage with the 50 inner ratchet surface of the member 17. As shown, the member 18 is also provided with a protruding extension or dog 21 so that through the engagement and disengagement of this dog by outside mechanism, hereinafter described, the 55 power of the sleeve 16 may be disconnected from or connected to the drum 20.

Herein, this connection or disconnection is controlled by a member 22, suitably guided at its free end on the casting 7 and pivotally connected 60 at 23 to the base of the tone arm 3 and adapted, as the tone arm is swung laterally about its usual vertical pivot 24 provided on the supporting frame, to project into the path of the member 21 or be moved out of the path of the same in such 65 manner as to cause the automatic disconnection 70

or connection of the driving sleeve 16 to the drum 20. Thus, when the tone arm or reproducer mechanism is in the position shown in full lines in Fig. 1, i. e. the position which it would occupy after the reproduction of a record, and while 5 still engaging the groove therein, the member 22 is pushed laterally out of the path of the dog 21 by a depending extension 25 on a lower frame 26 swinging with the tone arm, so that the dog connection 18, under urge of its spring engages 10 ratchet 17 and power is thus automatically connected to the drum 20 to cause the latter to make a revolution.

This drum controls the movement of the reproducer mechanism, causing it to be raised from 15 the record, swung back, and returned and lowered on another record. As shown, it is provided with a longitudinally grooved portion disposed at the top of the drum when the latter is stationary, and having spaced inclined surfaces 27 and 28 20 forming its bottom and, like the groove, extending the whole length of the drum. Of these, since the drum rotates in the direction of the arrow shown in Fig. 2, the surface 27 forms a reproducer elevating surface, while the surface 28 forms a 25 lowering surface. Means are also provided on the drum and cooperating with the reproducer to guide and control it in its movement between elevating and lowering positions.

More particularly, it will be noted (see Fig. 2) 30 that when the reproducer mechanism is in the full-line position shown in Figs. 1 and 2, the surface 27, upon rotation of the drum 20, will engage a roller 29^a on a downwardly extending projection 29 which is out of contact with both 35 surfaces 27 and 28 during reproduction and carried by the previously mentioned lower swinging frame 26 and operative to elevate the tone arm as the projection 29 is elevated by the surface 27. It will here be noted that this projection 40 29 is provided on a member 30, which also carries the projection 25, and that both of these 45 projections are carried by the frame 26 which is attached to the lower end of the tone arm 3. Thus, since the latter arm is pivoted on a 45 transverse pivot at 32 on the supporting frame structure, the reproducer is correspondingly lifted as the projection 29 is lifted, this vertical movement of the reproducer being in addition to the lateral movement about the bearing 24. Thus, it will be clear that as the drum 20 rotates, the reproducer will be lifted from the record played and be free to be swung laterally. 50

Provision is also made for moving the reproducer laterally from this lifted position out beyond the edge of the record. Herein, this is accomplished by providing on the drum 20 a guide 33 extending longitudinally of the drum 20 and spirally on the outer surface thereof and, near the opposite end of the drum, laterally partway 60 around the drum, as shown in Figs. 1 and 10. As a result of the engagement of the finger 29 with this guide, the reproducer, upon continued rotation of the drum 20, will be swung laterally 65 toward the dotted-line position indicated in Fig. 1. Also, as the drum continues to rotate, the member 29 will be caused to follow the guide 33 around into a passage 33^a and from that into a communicating guide 34 which is so disposed 70 on the surface 28 as to lower the member 29 and thereby bring the reproducer arm back into reproducing position at the edge of a new record; it of course being understood that during the interval a new record has been substituted on 75

the table through mechanism hereinafter described.

Attention is here also directed to the fact that the drum 20 is so timed as to complete a revolution and have its dog 21 automatically disconnected and held out by the member 22 at the time or shortly after the reproducer is placed on the new record. It will also be noted that a coiled spring 22^a, connected between the tone 10 arm and the member 22 adjacent the pivot of the latter, acts not only normally to hold the member 22 in the path of the driving dog 21, but also acts to press the needle of the reproducer 4 over toward the grooved portion of the new 15 record by reason of the pressure exerted against the casting 7 by the member 22. It will also be noted that friction between the projection 29 and the guides 33, 34 and 33^a is minimized by the provision of a roller 29^a on the lower end of 20 the member 29.

Associated with the guide 34 is also herein a cooperating guide 35. The guide 34 herein is for lowering the reproducer onto a smaller record, as for example a ten-inch record, while the 25 guide 35 is for lowering it onto a larger record, as for example a twelve-inch record. As brought out above, if left to its normal path relative to the guide 33 and passage 33^a communicating therewith, the member 29 would always pass into the guide 34 since it will be noted that the end of the guide 35 is closed by the side wall of the passage 33^a. However, it is not always desired to play ten-inch records and, accordingly, improved controlling mechanism is 30 provided to bring the member 29 into one or the other of these guides 34, 35, depending upon the size of the record which is next to be supplied by the magazine. Hence, as this mechanism is connected to and cooperates with the magazine, 35 it is desirable to consider the record feeding or magazine mechanism before considering the use of the guide 35 more in detail.

In connection with the record feeding mechanism, it will be noted that the shaft 15 carries 40 a cam 36 outside the bearing 14. Moreover, this cam has fixed thereto an eccentrically disposed sprocket 37 whose pitch line is located exactly on the center of the shaft 15. This sprocket 37 is in turn connected by a chain 38 with a larger 45 sprocket 39 carried on the machine frame on a shaft 40 parallel to the shaft 15 but rotatable on an axis above the base 6 rather than below it. As shown, a chain tightener 41 is also provided, herein pivoted on a pin 42 on the frame and 50 carrying on a short arm a roller 43 engaging the cam 36 and on a longer arm a sprocket 44 movable between the chain reaches and engaging one reach of the chain. It will also be noted that due to the proportion between sprockets 37 55 and 39, the sprocket 39 will rotate only 90° while shaft 15 rotates one revolution. This rotation of the sprocket 39 also takes place while the drum 20 is rotating and holding the arm 3 in raised position with the member 29 disposed in 60 the guideway 33^a. Also, due to the arrangement of sprocket 37 eccentric to shaft 15, the sprocket 39 is enabled to stand still during a portion of the rotation of the sprocket 37, and while the latter is moved in its rotation about shaft 15 65 toward sprocket 39. It will also be evident that the chain tightener is adapted to compensate to keep slack out of the chain at all times, and that the shaft 40 will be rotated by the shaft 15 since the cam 36 and sprocket 37 are fixed to the 70 latter.

The record feeding mechanism is actuated by the shaft 40. Referring more particularly to Figs. 1 and 2, it will be noted that at the left of the table 2 a pair of horizontally disposed endless record feeding chains 45 is provided. As shown, 5 the right hand end of each of these chains passes around a four-toothed sprocket 46 on the shaft 40, herein between upwardly extending shaft bearings 47 and 48 provided on the main casting 7 and more closely adjacent the bearing 48. Further, 10 it will be noted that the opposite ends of these chains 45 pass around four-toothed idler sprockets 49 carried on a suitable shaft 50 parallel to the shaft 40 and journaled at its ends in suitable upwardly projecting bearings 51, 52 15 which, like the bearings 47 and 48, project above the base 6. Attention is here also directed to the fact that the chains 45 are provided with pins 53, Fig. 8, extending clear through from one chain to the other, and that these pins carry on 20 their outer ends rollers 54 which in turn move in suitable guides 55 in side frames 56. It will also be noted that inside the rollers suitable connecting members 57 are suitably provided carrying supporting means 58, and that these supporting 25 means carry record carrying members 59 and 60 disposed midway between adjacent pins 53, as shown in Fig. 7. Referring more particularly to Figs. 7 and 8 it will be noted that each of these members 59 and 60 is provided with a slot 61 30 therein adapted to receive the edge of a record and to support the record upright, the slot herein conforming to the curvature of the edge of the record, as shown in these figures and also in Fig. 1. Attention is moreover directed to the fact that 35 these members 59 and 60 are alternately disposed, and that the members 59 are shorter than the members 60. Thus, the members 59 constitute holders for twelve-inch records, while the members 60 constitute holders for ten-inch records, 40 and each of these members 59 and 60 disposed on the upper reaches of the chains 45, is adapted to receive a record inserted from the top in the slot therein. Moreover, it will be clear that these members 59 and 60 will feed their records to the 45 right and toward the table as the shaft 40 is rotated.

Considering Fig. 7 more particularly, it will be noted that the records are fed one by one from the vertical position in which they are carried 50 by the holders 59 and 60 into the inclined position above the table shown in that figure, and gradually lowered onto the table. Referring more particularly to Fig. 5, the wall of the central aperture in each record is caused to engage the bevelled upper end of the centering pin 62 on the table 2, and, as a result of its engagement with this pin, is moved slightly laterally, to the right, in such manner as to release the record from the downwardly traveling holder and permit the 60 record to settle into proper position relative to the pin 62 upon the table 2.

Attention is also directed to the fact that a suitable aperture 63 is provided in the base 6 beneath the conveyor mechanism thus provided, 65 so that the holders 59 and 60 may continue to pass downward beneath the mechanism and again come up at the left in Fig. 1 in position to receive another record. It will also be noted that the conveyor is so arranged herein that it will hold twelve 70 records, six ten-inch and six twelve-inch, although obviously the number may be varied as desired. It will also be evident that by leaving out one size or the other, all ten- or all twelve-inch records may be used, it thus being possible 75

to insert six records of either size desired, while by having any desired holder or holders empty, any desired sequence of records of varied sizes may be obtained.

5 Associated with this mechanism is improved reproducer controlling mechanism actuated by this mechanism and causing the reproducer mechanism to function automatically with whatever size of record is fed to the table. Herein, this controlling mechanism includes a cam 64 fixed on the shaft 40 closely adjacent the sprocket 39 and herein, as preferably, formed integral with that sprocket. As illustrated, this cam 64 is provided with two enlargements 65 disposed diametrically opposite one another, as shown in Fig. 2, and the cam also has opposite portions of uniform diameter 66 disposed between these enlargements 65. Cooperating with this cam is a roller 67 adapted to engage the surface 66 and, when actuated by 10 the enlargements 65, to actuate a frame 68. This frame 68 is in turn reciprocably mounted on the main frame within the limits of travel permitted by guide pins 69 and 70 disposed in a slot 71 in the member 68, a spring 72 disposed between 15 the pin 69 and the member 68 normally acting to hold the member 68 against the cam. Attention is also directed to the fact that an extension 73 is provided on the right hand end of the member 68 (Fig. 1), and that the member 68 is 20 slidably mounted in a suitable passage 74 provided in the main casting 7 (Fig. 2), so that this projection 73 may engage and cooperate with an upstanding projection 75 carried on the member 30 above the projection 25 previously described.

35 Considering more particularly the operation of this reproducer controlling mechanism, it will be noted that with the parts in the position shown in Fig. 1, the record played upon and shown to be completed is a ten-inch record delivered by a 40 holder 60, while the next record in the magazine is a twelve-inch record carried by a holder 59. Thus, when the drum 20 is started as a result of the disengagement of the member 22 from the member 21 by the member 25, the rotation of the 45 drum 20, through its surface 27 and the action of the depending projection 29, will cause the reproducer arm 3 to be raised, swung and, through the guide 33, swung back toward the guide 34 as earlier described. However, before its connected 50 arm 30 can swing back sufficiently to enable its projection 29 to enter the guide 34, one of the projections 65 on the cam 64 engages the roller 67 on the member 68 and consequently causes the projection 73 on the latter member to be moved 55 into the path of the lug 75 on the member 30. Further, at the time this lug 75 contacts with the lug 73, the depending projection or finger 29, which is then moving in the passage 33^a, will be directly in line with the closed end of the groove 35 on the drum 20. Hence, since the lug 73 will 60 prevent the reproducer mechanism from any further return toward the table, as the parts continue to operate the member 29 will be forced over the side of the passage 33^a forming the closed end of the groove 35, and into that groove. Obviously, after the member 29 has entered this groove, and as the drum 20 continues to operate, the reproducer 4 will be lowered onto the edge of a twelve-inch record as the projection 29 moves 65 down the slope 28, and pushed over into engagement with its groove by the springs 22^a. Further, the projection 75 will be automatically disengaged from the projection 73, leaving the reproducer then free to traverse the new record, 70 while the drum 20 will also be disconnected as 75

before described, after completing its revolution.

The next record deposited by the feeding mechanism, when all its holders are filled, will be a ten-inch record, and the next a twelve-inch record, etc. Thus, it will be evident that 5 the operations above described will be substantially repeated save that in the case of the ten-inch records the roller 67 will engage with the surfaces 66 and hence the projection 73 will not be moved out in into the path of the projection 75. 10 Instead, the projection 29 will be free to follow the guide 33 and passage 33^a past the end wall of the guide 35 and around until it passes into the slot 34, and the reproducer will be lowered by the surface 28 onto the edge of the smaller ten- 15 inch record and pushed over into engagement with the groove therein by the spring 22^a, as previously described.

During this movement of the reproducer relative to the record and before a new record is deposited, the record which has been played is discharged from the table. This is accomplished herein by the provision of a swinging arm or crank 76 formed on the end of the shaft 15 which is remote from the drum 20. As shown, this arm 25 76 is adapted to be rotated with the shaft from the inoperative position shown in Fig. 2 to the record discharging position shown in Fig. 6 while the end holder of the conveyor, i. e. the holder carrying the next record to be reproduced, 30 is moving the same about the shaft 40, as shown at the right in Fig. 7, toward centered position on the table. More particularly, it will be noted that this arm or crank 76 carries a roller 77 on its end and is so disposed as to be movable up beyond the edge of the table 2 through a slot 78 in the base 6 in such manner as to cause the roller to engage the projecting edge of the reproduced record, whether it be a ten-inch record or a twelve-inch record, and cause the same to 40 be elevated or tilted as shown in Fig. 6 in such manner as to clear the center pin 62 without conflicting with the new record which, by reason of the rotation of the drum shaft 15 and sprocket 37 through approximately 130°, is then moving 45 toward the table and is disposed at an angle of approximately 45° to the table as shown at the right in Fig. 7. As soon as one side of the reproduced record has thus been lifted and the pin 62 cleared, due to the rotation of the table 2 the 50 latter will cause the record to be discharged at the right in Figs. 1 and 2 due to the continued contact of one side of the record with one side of the rotating table. Herein, the record is propelled by the table over against a cushion 79 to 55 which it clings as it moves toward the right in Fig. 1 until it comes against an end cushion or guide 80. When it strikes 80, however, it is free to tilt downward against a guide 81 disposed angularly with respect to the guide 80. Then it 60 slides down between these guides into a suitable record compartment 82, preferably provided in a suitable drawer 83 in the bottom of the cabinet, the record automatically assuming the position in that drawer illustrated in Fig. 2. It will also 65 be understood that, due to the connection of the parts, after the reproduced record has thus been released from the pin 62 and discharged and while the new record moves further downward from the position thereof shown in Fig. 7, the 70 arm 76 swings around to its normal or depressed position and is below the table before the new record is deposited on the table by the conveyor mechanism as shown in Fig. 5.

Associated with the magazine mechanism is 75

also improved manually adjustable controlling mechanism, also having certain new automatic features. Herein it will be noted that the shaft 40 passes through both of the sprockets 46 and 5 at a point beyond its bearing 48 carries an eight-tooth sprocket 84. This sprocket 84 is in turn connected by a chain 85 with an eight-tooth idler sprocket 86 spaced to the left thereof, as shown in Fig. 3. As illustrated in Figs. 1 and 3, a casing 10 87 is provided having a slot 88 therein in its top and a plurality of numerals disposed along the slot between the slot and the conveyor mechanism. Herein, these numerals from left to right are "12", "11", "10", etc. down to "1", corresponding to the number of exposed holders 59 and 60 15 on the top of magazine chains. At the right of the "1" a "0" is provided. Cooperating with the chain and these numerals is a control knob 89 permanently fixed, as at 90, to the chain 85 and 20 adapted, by reason of improved clutch mechanism hereinafter described, to be reciprocated manually to any desired position along the slot and also moved automatically along the latter, a suitable pointer 91 being provided on the knob 25 for indicating purposes. More particularly, it will be noted that the sprocket 84 is located on the end of the shaft 40 and carried on a clutch member 92 coaxial with the shaft 40. This member 92 has on its inner end four notches adapted 30 to cooperate with a like number of notches on a reciprocating member 93 likewise on the shaft and having a slot 94 cooperating with a pin 95 on the shaft, the member 93 being movable to compress a coiled spring 96 carried on the shaft 35 and held in position thereon by a pin 97. Thus, it will be evident that the pointer 91 on the knob 89 is movable with the shaft 40, or relative to the slot 88 independently of the shaft 40, and is maintained in timed relation with the record supports 59 and 60 so that the pointer is always 40 opposite a record holder.

Cooperating with this control mechanism in an improved manner is also switch mechanism including a pivoted switch member 98. This member 98 controls a suitable motor switch 99 which is connected in one of the motor leads 100 extending between a suitable socket 101 and the motor 1. Herein, this switch lever 98 is adapted to assume the "off" position illustrated 45 in dotted lines in Fig. 1 and the "on" position illustrated in full lines therein, wherein it extends in the path of the knob 89. Thus, when the knob 89 continues to move to the right, it will engage this lever and throw it into circuit breaking position, thereby interrupting the current flow to the motor and stopping the machine. Preferably, as herein, a "stop" button marked 50 "S" and similar to those carrying the numerals, is also provided opposite the position of the pointer 91 when the switch is disconnected and at the right of the button marked "0", so that this position of the knob will also be indicated.

Associated with the mechanisms described, is also rejector mechanism, i. e. mechanism adapted 55 to discharge a record when for any reason it is desired to discontinue its reproduction. This mechanism herein includes a pivoted member 102 pivoted at 103 on a depending part of the main casting below the member 22 and extending upward at one side of that member and movable across the path thereof. Thus, by connecting a rod 104 to the depending end of this member 102 and extending this rod below the member 22 and out through the side of the casing and 60 75 providing a knob 105 thereon, it is made possible

for the member 22 to be pushed out of engagement with the member 21 at any time and thus cause the reproducer to be swung back from the record then on the table, and another record substituted in the manner previously described. 5

Attention is also directed to the fact that the swinging reproducer mechanism pivoted on the transverse pivot 32 is also herein provided with suitable counterbalancing means 106 carried on an extension 107 at the opposite side of the pivot from the drum 20 and suitably adjustably attached, as by a setscrew 108. As a result of this adjustable weight, it is made possible to vary the weight on the reproducer needle as may be desired and also to adjust the control mechanism 15 below the base. 15

Attention is also directed to the arrangement of the cabinet shown in Figs. 1 and 2, wherein the discharged record chute is at one end of the table 2, space is provided for the needle box 20 109 or the like at one side thereof, the record drawer 83 is conveniently accessible through the end wall 80 and located below the chute, and the sound opening 110 is disposed below the inner end of the tone arm; thereby producing an exceedingly compact and convenient arrangement 25 wherein only a minimum of mechanism is above the base 6. It will of course also be understood that the structure may be embodied in a cabinet 30 having a side door or a pivoted top, as desired. 30

Considering the operation of the mechanism as a whole, it will be evident that the magazine presented by the upper holders 59 and 60 may be filled from the top with facility, it only being necessary to seat six ten-inch records in the 35 grooves 61 in the holders 60 and six twelve-inch records in the corresponding grooves in the holders 59. If it is desired to play all of the records, the control knob 89 will be moved to the left in Fig. 1 until its pointer is opposite 40 the number "12", the clutch mechanism 92, 93, etc. permitting free movement of the knob relative to the shaft 40 and always keeping the pointer opposite one of the record holders. If it is desired to play any number less than twelve, the 45 knob is correspondingly adjusted to a position opposite the number desired. When in the desired position, the switch lever 98 is thrown to the left to start the motor and the automatic operation of the machine is begun. This automatic operation will continue, successive records of different size being placed upon the table, reproduced, and discharged, all as hereinabove described and while the table continues to rotate, until the magazine is empty. Thereafter, if the 50 switch lever 98 has not been previously thrown to "off" position, the knob 89 will engage this lever and throw it to the right to "off" position in such manner as to open the switch and shut down the machine. 60

If it is desired to reproduce records of only one size, my improved mechanism makes it possible to do this, it only being necessary to insert the records of the desired size in their proper holders and leave the other holders empty. 65 Thus, for example, six twelve-inch records may be automatically reproduced, or six ten-inch records. It will also be evident that any combination or sequence of records of different size may also be obtained by leaving certain holders 70 empty. Further, it will be noted that no manual intervention is necessary to set or change the mechanism to adapt it to operate when records of only one size are to be reproduced or when certain holders are empty. This will be clear 75

when it is considered that when a holder is empty and hence does not deliver a record onto the table, the driving dog 21 is released as a result of the reproducer dropping below the surface of the turntable and swinging the reproducer arm 3 about the pivot 32 and pulling the member 22 out of engagement with the dog 21, the member 22 then being pulled longitudinally away from 21. When this occurs, the machine will go through a record substituting operation without the reproducer having any connection with the record, and the parts will thereafter automatically take up their automatic operation upon the next record. Attention is also directed to the fact that the parts are so timed that if desired any one or more of the ten-inch or twelve-inch records in a completely filled magazine, or any one or more of the ten or twelve-inch records when records of only one size are being played, may be removed after once being inserted in the holders, all without in any way disarranging the mechanism, the machine instead going through its various operations just as if all the spaces in the magazine were filled and taking care of the next record after the empty holder or holders entirely automatically and whether it is a ten-inch or a twelve-inch record.

As a result of my improved reproducer controlling mechanism, it will also be noted that no intervention is required on the part of the operator in order to adjust the reproducer mechanism of the machine when two sizes are in the magazine. More particularly, it will be noted that through the improved control mechanism provided, the needle is automatically placed in proper position upon the edge of a ten-inch record or a twelve-inch record with a gentle lowering movement and then, regardless of the size of the record, gently and automatically moved laterally by its spring toward the first or outer record groove in such manner as to bring about the reproduction of the record regardless of its size.

Here attention is also directed to the fact that through the provision of my improved eccentric sprocket, cam, and chain tightener mechanism, it is made possible to provide ample time for returning the reproducer to the record after the record has been deposited on the turntable and before the driving dog returns to normal position. This will be clear when it is considered that the sprocket on the shaft 40 is enabled to stand still during a portion of the rotation of the eccentric sprocket 37, thereby giving plenty of time to return the reproducer. Attention is further directed to the improved operation of the reproducer and discharge mechanism made possible by the provision of the drum or cam means controlling the reproducer arm and the provision of cam means for operating the record discharge roller, with both the reproducer cam means and the discharge cam means controlled by the reproducer through the clutch. Thus, not only is the reproducer enabled to cause both its cam means and the discharging cam means to be set in operation upon the completion of reproduction, but both the reproducer and the discharge means are operated positively and in such timed relation as substantially to reduce the interval between reproductions.

It will also be noted that the condition of the machine during operation is always indicated by the control knob 89, which advances one numeral to the right for every record substituting operation of the machine, the movement of the knob relative to the slot and the numerals providing

an exceedingly convenient and readily readable indicating means. Further, with this indicating means disposed closely adjacent the records and so arranged that the positions of the knob register with the positions of the records, it is made exceedingly convenient in use. For example, if with a filled magazine it is desired to play only four records or up to and including a known record, movement of the knob until its pointer 91 is opposite "4" or the known record, brings about the desired result.

As a result of my improved magazine mechanism, it will also be noted that I have made it exceedingly convenient to insert records, it only being necessary to drop the bottom edge of the selected record into the slot in the record holder, an operation which is very quick and convenient. Moreover, it will be evident that at any time prior to its depositing operation on the table, any record in the magazine may be removed by simply lifting it out of the slot 61, and any other record substituted. Thus, it will be evident that not only is the operation of inserting records made exceedingly simple, easy, and quick, but it is made possible to change one's mind as to the records in the magazine constituted by the holders 59 and 60 and substitute others at any time prior to the actual deposit of the records on the table and without interrupting the reproduction of the other records. Later, even if a record is being reproduced, its reproduction may also be immediately discontinued by simply punching in the rejector.

In connection with the record feeding mechanism, attention is also directed to the exceedingly simple, effective, and silent character of my record depositing means. More particularly, it will be noted that as the holders come down toward parallelism with the table, the engagement of the usual pin aperture in the record with the table pin acts automatically to move the record laterally relative to the slot in the holder in such manner as, while the holder continues to move down, to cause the record to be automatically disengaged from the slot and, under the guidance of the pin, to settle down very quickly and quietly into playing position upon the table, the noise resulting from record movement being thus minimized at the same time that the necessity for providing additional guides, pads, or the like is also eliminated.

Here attention is also directed to the fact that my improved construction makes it possible for records to be substantially simultaneously delivered to and discharged from the table in such manner as to expedite the operation of the machine. More particularly, it will be noted that each record holder moves its record from its upright position shown in Figure 7 substantially to the angular position indicated at the right in that figure, while the reproduced record is being discharged by the discharge arm, and that the latter moves from its downwardly disposed position shown in Figure 2 to the position shown in Figure 6 while the new record is moving as set forth. Attention is further directed to the fact that the new record moves in over the table from the direction of the magazine and angularly downward toward centered position, while the reproduced record is lifted at one side and discharged away from the new record, all in such manner as to prevent conflict while enabling the new record to be seated in centered position on the table very promptly after the old record has been disengaged.

gaged from the pin and discharged from the table.

Attention is further directed to the fact that as a result of a new coordination of the several mechanisms relative to the discharge mechanism, my improved structure makes it possible for the reproducer mechanism or the feeding mechanism, and herein both, to cooperate in a new timed relation with the discharging mechanism and one wholly incapable of being obtained with prior discharging mechanisms. Thus, while my swinging discharging member is swinging from its normal position during reproduction through its cycle to discharge a record and return to this normal position, the reproducer mechanism is simultaneously moved away from the reproduced record and out of the path of the discharged record and back again into engagement with the next record to be reproduced, reaching the latter substantially simultaneously with the completion of the movement of the discharge member. Further, it will be noted that the feeding mechanism also cooperates at its proper place in this new coordinated action, the same acting to present a new record in the path of the reproducer substantially simultaneously with the discharge of the reproduced record before the above described return movement of the reproducer mechanism which is completed substantially simultaneously with the return of the discharging member to its normal position. As a result of this improvement, it will be noted that not only is a markedly improved and simplified structure made possible, but one in which there is a new relative operation and timing of the reproducer mechanism or feeding mechanism relative to the operation of the discharge member, and such a new coordination as to enable the mechanism to operate very rapidly and also to enable the mechanism to be used under varied conditions permitting a long discharge movement and to which the discharge mechanisms of the prior art are obviously unadapted.

Attention is further directed to the fact that my mechanism is such that while obtaining automatic reproduction of records and effecting a marked reduction in the length of the silent interval between reproductions, it is still made possible to use a record rotating table rotatable in fixed planes throughout the operation of the phonograph. Thus, I am able to eliminate previously necessary table feeding movements and also changes in the table drive, while also having the table rotating throughout the operation of the phonograph. Also, I am able to avoid spring supporting means for the table and the difficulties inherent with such spring supported tables, wherein the height of the table must vary with the weight thereon, and, of course, be different while records of different diameter are being reproduced. In connection with my improved mechanism, it will also be noted that all necessity for stringing records on an axial record supporting member extending through the record apertures is also eliminated. Instead, in my improved mechanism wherein the records are supported extraneously of the record apertures, the records awaiting reproduction are readily changeable at will at any time prior to delivery to the table, by simply withdrawing them edgewise from the magazine, all without requiring that reproduction be stopped during record changes, or requiring that any record or records other than those desired to be substituted, be removed. Here it will also be observed that the disposition of the

records in substantially upright position in the magazine also markedly facilitates such withdrawal and the insertion of new records. At the same time that I am able to obtain the above advantages, it is also made possible to reproduce either successive records of small diameter or successive records of a larger diameter, or mixed records, i. e. records of different diameter arranged in any desired order, and to reproduce the successive records despite variations in diameter and without interrupting or in any way changing the rotation of the record rotating table.

It will also be evident that while adapted to use to reproduce a series of records, my improved machine is also adapted to use with only one record. Its structure is such also as to make repeating of a record very convenient, it only being necessary to insert the discharged record in the next holder, if necessary rejecting the record which has been placed on the table in the meantime.

As regards the general construction, attention is also directed to the general arrangement of the mechanism which enables it to be inserted in a usual cabinet space, and also to the simplicity of the mechanism and the small number of parts, as well as to the simplicity of the parts used, all of which are adapted to be made in ordinary production and the machines thus being adapted to be readily and economically produced. These and other advantages of my improved construction will, however, be clearly apparent to those skilled in the art.

In the claims herein when I refer to standard records, it will be understood that I contemplate records of usual standard types as distinguished from special records having contacts or the like inserted therein. Further, where I refer to mixed records, it will be understood that I refer to records which are not of the same diameter.

While I have in this application specifically described one embodiment which my invention may assume in practice, it will be understood that the same is shown herein for illustrative purposes only, and that the invention is not limited thereto but may be modified and embodied in various other forms without departing from its spirit or the scope of the appended claims.

What I claim as new and desire to secure by Letters Patent is:—

1. In a phonograph, a magazine supporting a plurality of records of different predetermined diameters and having means for permitting edge-wise withdrawal of any record therein, a single laterally offset record rotating table having upright record centering means and rotatable on a vertical axis in playing position throughout the operation of the phonograph, means for rotating said table throughout said operation, means for automatically feeding successive records of the same or different diameter laterally from said magazine into centered position on said table while the latter rotates, and reproducing mechanism successively automatically reproducing said records of different diameter on said table. 65

2. In a phonograph, a magazine carrying axially apertured records of different diameter, a single laterally offset record rotating means having an axial centering pin, said record rotating means being of a fixed height and rotatable on a vertical axis in playing position, means for rotating said record rotating means throughout the operation of the phonograph, record feeding mechanism wholly extraneous of the record apertures for automatically delivering successive rec- 75

- ords of different diameter in said magazine successively into centered position on said rotating means, reproducing mechanism successively automatically reproducing said records as centered on said rotating means irrespective of their differences in diameter, and record discharging means other than said feeding mechanism for successively automatically discharging the reproduced records.
- 5 10. 3. In a phonograph, a magazine receiving records of different predetermined diameters in substantially upright position therein, a single laterally offset record rotating table rotatable on a vertical axis in fixed horizontal planes, means for rotating said table throughout the operation of the phonograph, means for automatically feeding successive records of different diameter laterally from said magazine directly onto said table while the latter rotates, mechanism for automatically 15 reproducing said successive records of different diameter as successively centered on said table, and record discharging means other than said feeding mechanism for successively automatically discharging the reproduced records.
- 15 20. 4. In a phonograph, a magazine supporting simultaneously records of different predetermined diameters in substantially upright position therein, feeding mechanism for automatically feeding laterally successive records of different predetermined sizes in said magazine, a laterally offset record rotating table in alignment with said magazine rotatable on a vertical axis in fixed horizontal planes, means for rotating said table on said axis throughout the operation of the phonograph, a centering pin on said table receiving records directly from said lateral feeding mechanism and centering the same, and mechanism automatically operative to reproduce said successive records of different diameter as deposited on 25 said table.
- 25 30. 5. In a phonograph, a magazine supporting a plurality of records, a laterally offset record rotating table rotatable on a vertical axis throughout the operation of the phonograph, mechanism for automatically feeding successive records from said magazine into centered position on said table having means for moving said magazine laterally to dispose records therein over said table and also having cooperating record centering means, reproducing mechanism successively automatically 35 reproducing said records on said table, and discharging mechanism successively automatically discharging the reproduced records from said table.
- 35 40. 6. In a phonograph, a magazine supporting a plurality of records, a laterally offset record rotating table rotatable on a vertical axis throughout the operation of the phonograph, mechanism for automatically feeding successive records in said magazine into centered position over said table having means for moving said magazine laterally relative to said table to project the records laterally relative to the other records therein and over said table and also having co-operating relatively 45 fixed centering means toward which said magazine is moved and engaged by the records therein, and reproducing mechanism successively automatically reproducing said records on said table.
- 45 50. 7. In a phonograph, a magazine supporting a plurality of records of different predetermined diameters, a laterally offset record rotating table rotatable on a vertical axis, mechanism for automatically feeding successive records of different diameter from said magazine into centered position on said table having means for moving said
- 55 60. magazine to dispose records therein over said table and also having co-operating centering means, reproducing mechanism successively automatically reproducing said records on said table, and discharging mechanism successively automatically discharging said records from said table.
- 60 65. 8. In a phonograph, a magazine supporting a plurality of records of different predetermined diameters, a laterally offset record rotating table 10 rotatable on a vertical axis, mechanism for automatically feeding successive records of different diameter in said magazine into centered position over said table having means for moving said magazine laterally relative to said table to project 15 records laterally relative to the other records in said magazine and over said table and also having co-operating centering means, reproducing mechanism successively automatically reproducing said records on said table, and discharging mechanism successively automatically discharging said 20 records from said table.
- 65 70. 9. In a phonograph, a magazine supporting a plurality of records, a laterally offset record rotating table 15 rotatable on a vertical axis, mechanism for automatically feeding successive records from said magazine into centered position over said table having means for moving said magazine to dispose records therein over said table and also having co-operating centering means, reproducing mechanism successively automatically reproducing said records on said table, and discharging mechanism disposed during reproduction 25 below a record on said table and successively automatically discharging said records from said 30 table.
- 70 75. 10. In a phonograph, a magazine receiving from the top thereof records of different predetermined diameters and having record supporting means extraneous of the records and below the same, a laterally offset record rotating table rotatable on a vertical axis, means for automatically feeding said magazine to deliver successive records of different diameter into centered position on said table, reproducing mechanism successively automatically reproducing said records on said table, and discharging mechanism successively automatically discharging said records from said table.
- 75 80. 11. In a phonograph, a magazine supporting a plurality of records, a laterally offset record rotating table rotatable on a vertical axis, mechanism for automatically feeding successive records from said magazine into centered position on said table having means for moving said magazine to dispose records therein over said table and also having co-operating record centering means, reproducing mechanism successively automatically reproducing said records on said table, and discharging mechanism successively automatically discharging the reproduced records from said table, said feeding and discharging mechanisms being simultaneously operative on records disposed over the table while inhibiting conflict between the records.
- 80 85. 12. In a phonograph, record feeding mechanism receiving mixed records of different predetermined diameters in substantially upright position therein and feeding said records therefrom in any order of arrangement therein into reproducing position, a horizontal record rotating table rotatable on a stationary axis in substantial alignment with the axes of records in said feeding mechanism and having upstanding axial centering means thereon and receiving said records one 90

- by one from said mechanism while said table is in playing position, and mechanism for automatically reproducing said records successively as they are successively delivered in centered position on said table.
13. In a phonograph, record feeding mechanism receiving mixed records of different predetermined diameters in substantially upright position and having means for feeding records in any order of arrangement in said mechanism into reproducing position, a horizontal record rotating table rotatable on a stationary axis in substantial alignment with the axes of the records in said feeding mechanism and having upstanding axial centering means thereon receiving said records one by one from said feeding means while said table is rotating in playing position, means for rotating said table throughout the operation of the phonograph, mechanism for automatically reproducing said records successively as they are successively delivered on said rotating table, and means for automatically removing said reproduced records from said table as they are successively reproduced and while said table continues to rotate in playing position.
14. In a phonograph, record feeding mechanism receiving mixed records of different predetermined diameters in substantially upright position therein and feeding said records in any order into reproducing position, a horizontal record rotating table receiving said records one by one from said mechanism while said table is rotating in playing position, means for rotating said table in said position throughout the operation of the phonograph, mechanism for automatically reproducing said records successively as they are successively delivered on said table, and means other than said feeding mechanism and likewise operative while said table is rotating for automatically discharging said reproduced records as they are successively reproduced.
15. In a phonograph, record feeding mechanism receiving records of different predetermined sizes simultaneously in different predetermined positions therein and feeding said records simultaneously step by step toward delivering position, a horizontal record rotating table receiving said records one by one from said mechanism and disposed in alignment with the path of record movement toward delivery position, and mechanism for automatically reproducing said records successively as they are successively delivered on said table.
16. In a phonograph, record feeding mechanism carrying records of different predetermined sizes simultaneously in different predetermined positions therein and feeding said records longitudinally of said mechanism, a record rotating table rotatable on a fixed axis and receiving records one by one from said mechanism and in alignment with said mechanism, mechanism for automatically reproducing said records successively as they are fed on to said table, and separate mechanism for successively effecting discharge of said records from said table as they are reproduced.
17. In a phonograph, a record rotating table rotatable on a fixed axis, record feeding mechanism having means for supporting records of different predetermined diameters simultaneously in different predetermined positions therein and delivering said records directly on to said table while the latter is in reproducing position, mechanism automatically operative successively to reproduce records of one diameter as fed directly on to said table, and means for automatically adjusting said mechanism to reproduce records of the other diameter as fed on to said table.
18. In a phonograph, a record rotating table, record feeding mechanism having a plurality of record receptacles filled from the top and receiving records of different predetermined diameters simultaneously and means for feeding said records successively into reproducing position, actuating said receptacles to deliver records directly on said table and mechanism for automatically reproducing said records successively as they are fed into reproducing position by said feeding mechanism.
19. In a phonograph, a horizontal record rotating table, record feeding mechanism having a plurality of record receptacles for records of different size alternately disposed in series and receiving records of different predetermined diameters simultaneously and means for feeding said records successively on to said table actuating said receptacles to deliver records directly on said table, and mechanism for automatically reproducing said records successively on said table as they are fed thereto by said feeding mechanism.
20. In a phonograph, a record rotating table, record feeding mechanism having a plurality of record receptacles receiving records of different predetermined diameter simultaneously and means for feeding said records simultaneously toward reproducing position and successively into that position, actuating said receptacles to deliver records directly on said table, and mechanism comprising a reproducer and a single record rotating table receiving said records from said feeding mechanism for automatically reproducing said records successively as they are successively fed into reproducing position by said feeding mechanism.
21. In a phonograph, a record rotating table rotatable on a fixed axis, record feeding mechanism including a plurality of record carriers carrying records of different predetermined diameter simultaneously and feeding said records successively directly on to said table, and mechanism for automatically reproducing successively on said table any records in said feeding mechanism irrespective of whether certain of said carriers are empty.
22. In a phonograph, record feeding mechanism including a plurality of record carriers carrying records of different diameter simultaneously and means for feeding said records simultaneously toward reproducing position, actuating said carriers to deliver records into said position, and mechanism including a single rotating table receiving said records successively thereon for automatically reproducing successively any records in said feeding mechanism as they are successively fed into reproducing position irrespective of whether they are all of the same diameter or of different diameters.
23. In a phonograph, record reproducing mechanism including a single horizontal table and a reproducer, and means located at one side of the table and engaging the lower edges of a series of substantially upright records therein for feeding said records bodily laterally toward the table axis above the table and successively tilting the end record adjacent the table directly into reproducing position on the latter.
24. In a phonograph, record reproducing mechanism including a single horizontal record rotating table and means for rotating said table throughout the operation of the phonograph, and

- endless carrier means located at one side of said table and engaging the lower edges of substantially upright disc records for successively feeding the nearest record on said carrier means into 5 reproducing position on said table while the latter is rotating.
25. In a phonograph, record reproducing mechanism including a single horizontal table and a reproducer, and means located at one side of said table and engaging the lower edges of a series of substantially upright records of different diameter 10 therein for successively feeding said records into reproducing position on said table.
26. In a phonograph, record reproducing mechanism including a single horizontal table and means for rotating said table throughout the 15 operation of the phonograph, and mechanism including an endless flexible conveyor disposed at one side of said table, record carriers thereon, and means for actuating said conveyor and carriers to successively feed a series of records carried by said carriers directly into reproducing position on said table while the latter is rotating.
27. In a phonograph, a plurality of aligned 20 holders each adapted to carry an outwardly extending record, a horizontal table in alignment with said holders, and means for successively tilting said holders and delivering the records therein on the table.
28. In a phonograph, a conveyor carrying a plurality of holders each adapted to receive the edge of an outwardly extending record, a horizontal table in alignment with said conveyor, and means for successively tilting said holders and delivering 25 records on the table.
29. In combination, a horizontal record rotating table having a centering pin, a horizontally moving conveyor carrying a record holder adapted to carry a record above the same, and means for tilting said holder and bringing the aperture in the record over said pin.
30. In combination, a single horizontal record 30 rotating table having a record centering pin, a conveyor carrying a series of record holders at one side of said table, and means for progressively feeding said holders to deliver said records successively in centered position on said pin.
31. In a phonograph, record feeding mechanism including a plurality of holders presenting openings 35 each receiving the bottom edge of a record and supporting the record in substantially upright position, an endless flexible support for said holders, a record rotating table, and means for actuating said holders to deliver records therein in centered position on said table.
32. In a phonograph, a record feeding mechanism comprising a series of holders of different height and alternately receiving the bottom edges 40 of records of different size and supporting the records in substantially upright position, an endless flexible support for said holders, a record rotating table, and means for actuating said support and holders to deliver records in the latter in centered position on said table.
33. In combination, a record rotating table having a central pin, a record holder at one side of said table for carrying the edge of an axially apertured record, and means for bringing a wall 45 of the aperture in a record in said holder into engagement with said pin to release said record from said holder.
34. In combination, a record rotating table having a central pin, a record holder at one side of said table for carrying the edge of an axially 50 apertured record, and means for bringing a wall of the aperture in a record in said holder into engagement with said pin to release said record from said holder.
35. In combination, a record rotating table having a central pin, a record holder at one side of said table engaging the bottom edge of an axially apertured record and holding the record in substantially upright position, and means for 55 tilting said holder bringing a wall of the aperture in a record therein into engagement with said pin to disengage the record from said holder.
36. In combination, a record rotating table having a central pin, a record holder at one side of said table for carrying the bottom edge of an axially apertured record, means for swinging said record over said table, and means for effecting a lateral releasing movement of said record from said holder when the wall of the aperture in the 60 former engages said pin.
37. A phonograph having a magazine receiving records in a substantially upright position therein, a record rotating means engageable by a record and rotatable on a stationary axis, means 65 rotating the same about said axis throughout the operation of the phonograph, means for automatically supplying successive records of the same or different predetermined diameters to said record rotating means from said magazine while said record rotating means is rotating, and means for successively automatically reproducing 70 said records regardless of their variations in diameter as they are successively supplied to said rotating means.
38. A phonograph having a record rotating means rotatable on a fixed axis, means rotating the same about said axis throughout the operation of the phonograph, record receiving means receiving records of different diameter and permitting edgewise withdrawal of any record therein, means for successively supplying records of different predetermined diameters in said receiving means to said rotating means while the latter is rotating, means for successively automatically reproducing 75 said records regardless of their variations in diameter as they are successively supplied to said rotating means, and means other than said supplying means for successively automatically removing the reproduced records regardless of their variations in diameter and likewise operative while said rotating means is rotating.
39. A phonograph having a record magazine receiving records of different diameter in substantially upright position therein, a record rotating means rotatable on a stationary axis, means rotating the same about said axis throughout the operation of the phonograph, means for successively supplying records of different predetermined diameters from said magazine to said record rotating means while said means is rotating, means for successively automatically reproducing said records regardless of their variations in diameter as they are successively supplied to 80 said rotating means, and means for successively automatically discharging the reproduced records regardless of their variations in diameter and likewise operative while said rotating means is rotating and disposed below the latter means 85 during reproduction.
40. A phonograph having a record rotating table rotatable in fixed planes on a fixed axis, means for rotating the same about said axis throughout the operation of the phonograph;

means for successively automatically reproducing standard records engaging successive records for reproduction while said records are on said table, and means operative while said table is rotating for substantially simultaneously discharging a reproduced record from said table and presenting in the path of said reproducer means a new record for reproduction thereby.

41. A phonograph having a record rotating table rotatable in fixed planes on a fixed axis, means for rotating the same in said planes about said axis throughout the operation of the phonograph, mechanism for reproducing standard records including a swinging reproducer engageable with successive records for reproduction while said records are on said table, and mechanism operative while said table is rotating for substantially simultaneously discharging a reproduced record from said table and presenting in the path of said reproducer a new record for reproduction thereby, said last mentioned mechanism including means for effecting the discharge of the reproduced record and swinging of the reproducer away from the reproduced record and subsequently moving the reproducer into playing position on the new record substantially within the time limits of operation of said record discharging means.

42. A phonograph having a record rotating table rotatable on a fixed axis, means for rotating the same about said axis throughout the operation of the phonograph, means for reproducing standard records including a swinging reproducer member engageable with successive records for reproduction while said records are on said table, mechanism operative while said table is rotating for discharging a reproduced record from said table and for substantially simultaneously feeding a new record into playing position on said table, said mechanism including means for effecting the discharge of the reproduced record from said table and feeding of the new record onto said table and the swinging of the reproducer member away from the reproduced record and subsequently swinging the same into playing position on the new record substantially within the time limits of operation of said record discharging means.

43. A phonograph having a record rotating table rotatable in fixed planes on a fixed axis, means for rotating the same about said axis throughout the operation of the phonograph, means for successively automatically reproducing records engaging successive records for reproduction while said records are on said table, and means operative while said table is rotating for discharging a reproduced record from said table and substantially simultaneously presenting in the path of said reproducer means a new record for reproduction thereby including a swinging record discharging member swinging to eject the reproduced record laterally from said rotating table and returning into position to cooperate with the next record, and controlling means for placing said reproducer mechanism on the new record substantially as said swinging member returns from a discharging operation.

44. A phonograph having a record rotating table rotatable on a fixed axis, means for rotating the same about said axis throughout the operation of the phonograph, means for successively automatically reproducing standard records of one diameter engaging successive records for reproduction while said records are on said table including a reproducer, and means operative

while said table is rotating for substantially simultaneously both discharging a reproduced record from said table and presenting in the path of said reproducer a new record for reproduction thereby with portions of both records simultaneously over the table during operation of said means, and means for adapting the phonograph for automatic operation on standard records of another diameter.

45. A phonograph having a record rotating table rotatable on a fixed axis, means for rotating the same about said axis throughout the operation of the phonograph, means for successively automatically reproducing records of one diameter engaging successive records for reproduction while said records are on said table, means operative while said table is rotating for discharging a reproduced record from said table and substantially simultaneously presenting in the path of said reproducer means a new record for reproduction thereby including a swinging record discharging member swinging to eject the reproduced record laterally from said table and returning into position to cooperate with the next record, controlling means for placing said reproducer mechanism on the new record substantially as said swinging member returns from a discharging operation, and means for adapting the phonograph for automatic operation on records of another diameter.

46. A phonograph having a record rotating table rotatable on a fixed axis, means for rotating the same about said axis throughout the operation of the phonograph, means for successively automatically reproducing standard records engaging successive records for reproduction while said records are on said table including a reproducer, means operative while said table is rotating for discharging a reproduced record from said table and substantially simultaneously presenting in the path of said reproducer a new record for reproduction thereby with portions of both records simultaneously over the table during operation of said means, and means for automatically adapting the phonograph for automatic operation on records of different diameters presented in mixed order to said reproducer mechanism.

47. A phonograph having a record rotating table rotatable on a fixed axis, means for rotating the same about said axis throughout the operation of the phonograph, means for successively automatically reproducing standard records engaging successive records for reproduction while said records are on said table, means operative while said table is rotating for discharging a reproduced record from said table and substantially simultaneously presenting in the path of said reproducer means a new record for reproduction thereby including a swinging record discharging member swinging to eject the reproduced record laterally from said rotating table and returning into position to cooperate with the next record and also controlling means for placing said reproducer mechanism on the new record substantially as said swinging member returns from a discharging operation, and means for automatically adapting the phonograph for automatic operation on records of different diameters presented in mixed order to said reproducer mechanism.

48. In a phonograph, record rotating means rotatable about a stationary axis, means for rotating the same about said axis throughout the operation of the phonograph, reproducer mechanism for reproducing a standard record of one

- diameter on said rotating means, means for discharging said record from said rotating means when said record is reproduced and while said rotating means is rotating and for substantially 5 simultaneously presenting a new standard record in the path of said reproducer mechanism while said record rotating means is rotating, and means for adapting the phonograph for automatic operation on standard records of another diameter.
- 10 49. A phonograph having record magazine means receiving axially apertured records of different diameter and wholly extraneous of the record apertures, a record rotating means rotatable on a fixed axis, means for rotating the same throughout the operation of the phonograph, means for successively supplying records of different predetermined diameters thereto while said record rotating means is rotating, means for successively automatically reproducing said supplied records on said rotating means regardless of their variations in diameter, and means likewise operative while said rotating means is rotating and other than said record supplying means for automatically successively discharging the reproduced records regardless of their variations in diameter.
- 15 50. A phonograph having a magazine receiving records of different diameter while maintaining the record apertures free from obstruction to lateral record movement, record rotating means adapted to support a record during reproduction, means for rotating the same throughout the operation of the phonograph, means extraneous of the record apertures for successively automatically supplying from said magazine records of the same or different diameter to said rotating means operative while the latter is rotating, and means for successively automatically reproducing on said rotating means and discharging therefrom all records in said magazine as they are supplied from said magazine regardless of their variation in diameter and while said record rotating means remains in playing position and continues to rotate.
- 20 51. A phonograph having a record rotating table, means for rotating the same throughout the operation of the phonograph, movable reproducer mechanism, mechanism receiving records of different predetermined sizes in substantially upright position and having means for placing said records on the table while the latter rotates in playing position, mechanism for automatically placing the reproducer mechanism in initial playing position on each record supplied to the table regardless of the variation in size of the records, and mechanism movable relative to said record placing means for successively discharging the played records while said table remains in playing position.
- 25 52. A phonograph having a record supporting and positioning magazine having means disposed wholly extraneously of the supported records and adapted to carry records of different predetermined diameters for permitting record movement laterally relative to the other records therein at different points along the series of records in said magazine to effect changes in the program to be reproduced, record rotating means, means for rotating the same throughout the operation of the phonograph, means for successively supplying records of the same or different predetermined diameters from said magazine to said rotating means while the latter is rotating, and means for successively automatically reproducing said records as they are supplied regardless of their va-

riation in diameter and while said record rotating means remains in playing position and continues to rotate.

53. A phonograph having a record magazine adapted to carry simultaneously records of different predetermined diameters, a record rotating means, mechanism for automatically supplying successive records of the same or different predetermined diameters from said magazine to said rotating means while the latter is rotating comprising means for feeding all of the records in the magazine toward said rotating means and supplying the nearest record to the latter, and means for automatically successively reproducing the supplied records irrespective of their variations in diameter. 15

54. In a phonograph, a record rotating table rotatable on a stationary vertical axis and having an unobstructed record delivery space above the same, means for rotating the same about said axis throughout the operation of the phonograph, a record magazine having means for simultaneously supporting records of different diameter in substantially upright position therein and in laterally offset relation to said table, and means for automatically delivering successive records of different diameter in said magazine through said unobstructed space into centered position on said table. 20

55. In a phonograph, a record rotating table 30 rotatable on a stationary vertical axis and having an unobstructed record delivery space above the same, means for rotating the same about said axis throughout the operation of the phonograph, a record magazine having means for simultaneously supporting records of different diameter in substantially upright position therein and in laterally offset relation to said table, means for automatically delivering records of different diameter in said magazine through said unobstructed space 40 into centered position on said table irrespective of the sequence in which said records of different diameter are disposed in said magazine, and means for successively automatically reproducing said records irrespective of variations in diameter or sequence as said records are delivered to said table. 35

56. A phonograph having a record rotating mechanism, reproducer mechanism having a swinging reproducer, mechanism for automatically depositing the latter on the edge of a record including a clutch and clutch controlling member, and constantly operative means including a spring connected between said swinging reproducer and clutch controlling member urging the former toward reproduced position. 50

57. A phonograph having record rotating mechanism, reproducer mechanism having a swinging reproducer arm, mechanism for automatically depositing the latter on the edge of a record including a clutch and a clutch controlling member, and constantly operative means including an operative connection between said arm and said clutch controlling member urging the reproducer mechanism toward reproduced 60 position. 65

58. In a phonograph, record rotating mechanism, means for rotating the same throughout the operation of the phonograph, means extraneous of the record aperture for successively feeding to said record rotating mechanism records of the same size or different sizes while said mechanism rotates in playing position, swinging reproducer mechanism, means automatically operative to vary the swing thereof and deposit said 70 records. 75

reproducer mechanism in playing position on the edge of each fed record regardless of its size, and means extraneous of the record aperture for successively discharging the played records while said rotating mechanism remains in playing position.

59. In a phonograph, record rotating mechanism, means for rotating the same in playing position throughout the operation of the phonograph, movable reproducer mechanism automatically operative to effect reproduction of a record thereon of a predetermined size, record feeding mechanism for automatically feeding successive records of the same or different sizes to said rotating mechanism while said rotating mechanism is rotating, and automatically acting adjusting mechanism between said mechanisms and independent of the records for adjusting said reproducer mechanism to reproduce a record of another predetermined size.

60. In a phonograph, a record rotating table rotatable on a fixed axis, means for rotating said table throughout the operation of the phonograph, means for automatically delivering to said table successive records of different diameter while said table is rotating, a swinging reproducer, and automatically acting reproducer controlling mechanism operable independently of the records for automatically lowering said reproducer in different positions relative to the axis of said table to cooperate with records of different diameter.

61. In a phonograph, a swinging reproducer, and automatically acting reproducer controlling mechanism for lowering the reproducer in different positions to cooperate with records of different diameter comprising an intermittently acting reproducer supporting member, guiding means movable with said member, and means cooperating with said means and connected to said reproducer.

62. In a phonograph, a swinging reproducer, and controlling mechanism therefor including a rotatable member carrying raising and lowering surfaces and a guideway, a cooperating controlling member movable with said reproducer and engageable with said surfaces and guideway, means for rotating said first mentioned member having a clutch controlling the connection of said member thereto, and a member movable with said reproducer controlling said clutch.

63. In a phonograph, a swinging reproducer, and controlling mechanism therefor including a member carrying raising and lowering surfaces and a plurality of guideways therebetween, a cooperating controlling member movable with said reproducer and normally controlled by one guideway, and means for bringing the other guideway into control.

64. In a phonograph, record rotating mechanism, means for successively automatically discharging records of different diameter therefrom and substantially simultaneously presenting new records of the same or different diameter for reproduction on said rotating mechanism, a reproducer, reproducer controlling mechanism including a rotating cam and cooperating means movable with the reproducer and the cam and controlling the operation of both the reproducer and the cam, and means for automatically adapting the reproducer for operation on records of different diameter presented for reproduction on said record rotating mechanism.

65. In a phonograph, record rotating mechanism, a swinging reproducer, reproducer controlling mechanism including a rotating drum

and cooperating means movable with the reproducer and the drum and controlling the raising and lowering of the reproducer and the rotation of the drum, and record feeding mechanism controlling the co-operating means movable with the reproducer.

66. In a phonograph, record rotating mechanism, a swinging reproducer, and reproducer controlling mechanism including a rotating reproducer raising, lowering, and guiding drum, a member movable with the reproducer and engaging said drum, a clutch controlling the rotation of the drum, and a clutch controlling member movable with the reproducer.

67. In a phonograph, mechanism for successively presenting for reproduction and reproducing records including a record rotating table rotatable on a stationary vertical axis, means for rotating said table about said axis throughout the operation of the phonograph, a swinging record discharging member, reproducer mechanism automatically operative on successive records, on said table including a swinging reproducer, a record magazine having means extraneous of the record apertures for supporting a series of records in substantially upright position during reproduction of records on said table and means for successively feeding records from said supporting means through a different path from that of said discharging member, and means operative between reproducing operations of said reproducer and in timed relation to the movement of the latter for actuating said discharging member to discharge the reproduced record and return said discharging member to its initial position and, while said discharging member is performing said cycle of operation, effecting the delivery of a new record on to said table and thereafter depositing said reproducer on said new record.

68. In a phonograph, mechanism for successively presenting for reproduction and reproducing records of different diameter including a record rotating table rotatable on a stationary vertical axis, means for rotating said table on said axis throughout the operation of the phonograph, a swinging record discharging member, reproducer mechanism automatically operative on successive records of different diameter on said table including a swinging reproducer, a record magazine having means extraneous of the record apertures for simultaneously supporting a series of records of different diameter and means for successively feeding records from said supporting means through a different path from that of said discharging member, and means operative between reproducing operations of said reproducer and in timed relation to the movement of said reproducer for actuating said discharging member to discharge a record and return said member to its initial position and, while said discharging member is performing said cycle of operation, effecting the delivery of a new record of either diameter on to said table and thereafter depositing said reproducer on the new record.

69. In a phonograph, a reproducer controlling drum having a longitudinally extending depressed portion providing reproducer elevating and lowering surfaces and also having directing means between said surfaces, and reproducer mechanism having a controlling member engageable with said surfaces and said directing means and disposed in said depressed portion and out of contact therewith during reproduction.

70. In a phonograph, a reproducer controlling

drum having reproducer raising and lowering surfaces and a plurality of guiding means therebetween, a swinging reproducer having a member movable therewith and raised by said raising surface, and means for bringing said member into cooperation with either guiding means prior to engagement with said lowering surface.

71. In a phonograph, record rotating means rotatable on a vertical axis, means for rotating the same throughout the operation of the phonograph, record feeding mechanism for alternately delivering thereto records of different predetermined diameters while said means is rotating, reproducer mechanism operative on records on said rotating means, and means controlled by said feeding mechanism for alternately adjusting said reproducer mechanism to operate on records of different diameter.

72. In a phonograph, a single record rotating means rotatable on a vertical axis, reproducing mechanism operative on records thereon, record feeding mechanism having a plurality of individual record carriers in alignment with said record rotating means successively delivering records of different diameter directly to said rotating means, and means for automatically adjusting said reproducer mechanism to cooperate with a record of the diameter delivered by each carrier.

73. In a phonograph, record rotating means, reproducing mechanism co-operating with records on the latter, record feeding mechanism having a plurality of individual record carriers in alignment with said record rotating means successively delivering records of different diameter directly to said rotating means, and means controlled by said feeding mechanism independently of the records for automatically adjusting said reproducer mechanism to cooperate with a record of the diameter delivered by each carrier.

74. In a phonograph, record rotating means rotatable on a vertical axis, reproducing mechanism cooperating with records thereon, record feeding mechanism delivering on said rotating means records of different predetermined diameters and having a plurality of different carriers in alignment with said record rotating means and each delivering only a record of a certain diameter directly on said means, and means for automatically adjusting said reproducer mechanism to cooperate with the records delivered by different carriers.

75. In a phonograph, record rotating means, reproducing mechanism, record feeding mechanism adapted to deliver records of different predetermined diameters and having a plurality of different carriers in alignment with said record rotating means and each delivering only a record of a certain diameter directly on said means, and means for automatically adjusting said reproducer mechanism to cooperate with the records delivered by different carriers including a cam movable with the feeding mechanism and reproducer controlling mechanism controlled by said cam.

76. In a phonograph, record rotating means rotatable about a stationary axis and having means for rotating it about said axis throughout the operation of the phonograph, reproducer mechanism for automatically reproducing a record on said record rotating means, means for discharging said record from said rotating means when said record is reproduced and substantially simultaneously presenting a new record for reproduction by said reproducer mechanism, means

for automatically returning said reproducer mechanism and discharging means to cooperate successively with a newly presented record, and means for adapting the phonograph for like automatic operation on a record of another diameter.

77. In a phonograph, record rotating means rotatable in fixed planes about a stationary axis and having means for rotating said first mentioned means in said planes about said axis throughout the operation of the phonograph, reproducer mechanism for automatically reproducing a record on said record rotating means, and mechanism for effecting automatic reproduction and discharge of successive records on said record rotating means having means controlled by said reproducer mechanism for discharging a record from said rotating means when said record is reproduced and substantially simultaneously presenting a new record in the path of said reproducer mechanism and for automatically substantially simultaneously returning said reproducer mechanism and discharging means into position to cooperate successively with the new record.

78. In a phonograph, record rotating means rotatable in fixed planes about a stationary axis, means for rotating the same about said axis throughout the operation of the phonograph, reproducer mechanism for automatically reproducing a record on said rotating means, means for discharging said record from said rotating means when said record is reproduced and while said rotating means is rotating and substantially simultaneously presenting a new record for reproduction on said record rotating means while the latter is rotating, said means for discharging and presenting records including a swinging record discharging member, and means for actuating said reproducer mechanism and discharging member substantially simultaneously both when cooperating with a reproduced record and also when moved into positions to cooperate with a newly presented record.

79. In a phonograph, record rotating means rotatable about a stationary axis, means for rotating the same about said axis throughout the operation of the phonograph, reproducer mechanism for reproducing a record on said record rotating means including a swinging reproducer member, record discharging mechanism including a swinging record discharging member, mechanism for discharging a record from said rotating means when said record has been reproduced and substantially simultaneously presenting a new record on said record rotating means having power means and operative connections operated thereby for actuating said swinging reproducer and discharging members upon reproduction of a record and substantially simultaneously returning the same to cooperate with the new record, and means for adapting the phonograph for like automatic operation on records of a different diameter.

80. In a phonograph, record rotating means rotatable about a stationary axis, means for rotating the same about said axis throughout the operation of the phonograph, reproducer mechanism for reproducing a record on said record rotating means including a swinging reproducer member, record discharging mechanism including a swinging record discharging member, mechanism for discharging a standard record from said rotating means when said record has been reproduced and substantially simultaneously presenting a

new record on said record rotating means having power means and operative connections operated thereby and actuating said swinging discharge and reproducer members substantially simultaneously both when cooperating with a reproduced record and also when moved into position to cooperate with a new record, and means for automatically successively reproducing the presented records irrespective of variations in diameter thereof.

81. In a phonograph, record rotating means rotatable in fixed planes about a stationary axis, means for rotating the same about said axis throughout the operation of the phonograph, reproducer mechanism for reproducing a record on said record rotating means including a swinging reproducer member, record discharging mechanism including a swinging record discharging member, and mechanism for discharging a record from said rotating means when said record has been reproduced and substantially simultaneously presenting a new record on said record rotating means having power means controlled by said reproducer and cam means driven by said power means and positively actuating said swinging discharge and reproducer members upon reproduction of a record to effect discharge of the reproduced record and substantially simultaneously to return said swinging reproducer and discharge members for cooperation with the new record.

82. In a phonograph, record rotating means rotatable in fixed planes about a stationary axis, means for rotating the same about said axis throughout the operation of the phonograph, reproducer mechanism for reproducing a record on said record rotating means including a swinging reproducer member, record discharging mechanism including a swinging record discharging member, and mechanism for discharging a record from said rotating means when said record has been reproduced and substantially simultaneously presenting a new record on said record rotating means having a power connecting means controlled by said swinging reproducer, power means connected by said connecting means, and actuating means operated by said power means and actuating said swinging discharging and reproducer members substantially simultaneously both when cooperating with a reproduced record and also when returning each to cooperate with a new record.

83. In a phonograph, record rotating means rotatable about a stationary axis, means for rotating the same about said axis throughout the operation of the phonograph, reproducer mechanism for reproducing a record on said record rotating means including a swinging reproducer member, record discharging mechanism including a swinging record discharging member, mechanism for discharging a record from said rotating means when said record has been reproduced and substantially simultaneously presenting a new record on said record rotating means having power means and operative connections operated thereby and actuating said swinging discharge and reproducer members substantially simultaneously with respect to a reproduced record and also to return said members for cooperation with the new record, and means for adapting said mechanism to reproduce records of different diameters, and varying the swinging operation of said reproducer member for records of different diameters while maintaining the

swing of said discharging member the same for all records.

84. In a phonograph, record rotating means, reproducer mechanism for reproducing a record thereon, means for discharging said record from said rotating means when said record is reproduced and while said rotating means is rotating, and means for feeding a new record onto said record rotating means operative while the latter is rotating and disposing the new record over said rotating means in spaced relation above the reproduced record while the latter is still above said rotating means and being acted upon by said discharging means.

85. In a phonograph, a record rotating table rotatable about a stationary axis, means for rotating the same about said axis throughout the operation of the phonograph, reproducer mechanism for reproducing a standard record thereon, means for discharging said record from said table when said record is reproduced and for substantially simultaneously presenting a new record in the path of said reproducer mechanism while said table is rotating with portions of both records simultaneously over the table during operation of said means, and means for automatically adapting the phonograph for automatic reproduction and discharge of successive records of the same or different diameter successively presented to said reproducer mechanism.

86. In a phonograph, record rotating means, reproducer mechanism for automatically reproducing a record thereon, means for discharging said record from said rotating means when said record is reproduced and while said rotating means is rotating, means for feeding a new record into centered position on said record rotating means moving the new record into non-conflicting relation to the reproduced record above said rotating means while the latter is rotating and said discharging means is discharging the reproduced record away from centered position beneath the new record and delivering the new record in centered position on said rotating means substantially upon completion of the discharging operation, and means for automatically adapting the phonograph for automatic reproduction and discharge of successively presented records of the same or different diameter.

87. In a phonograph, record rotating means disposed in playing position throughout the operation of the phonograph, means for rotating said record rotating means throughout said operation, reproducer mechanism, raising and lowering means for the latter, record feeding mechanism, record discharging mechanism, power operated means for said raising and lowering means and said feeding and discharging mechanisms, and operative connections for initiating reproducer raising and record discharge upon reproduction and initiating record feeding movement toward said record rotating means to effect the delivery of a new record on said record rotating means substantially simultaneously with record discharge and discontinuing operation of said feeding mechanism prior to discontinuing operation of said discharging mechanism.

88. In a phonograph, record rotating means, means for rotating the same throughout the operation of the phonograph, reproducer mechanism, controlling means for the latter, record feeding mechanism, record discharging mechanism other than said feeding mechanism, and operative connections between said controlling means and said feeding mechanism having pro-

- vision for delaying the operation of said feeding mechanism and feeding a record toward said rotating means during a part of the movement of said discharging mechanism and completing record feeding by said feeding mechanism substantially within the time required to effect the cycle of movement of said discharging mechanism incident to each record discharging operation thereof.
9. In a phonograph, a record feeding mechanism including an endless mechanism carrying a series of upstanding holders receiving the lower edges of a series of records and supporting the same in substantially upright position, and a horizontal record rotating table at one side of said mechanism receiving successive records flatwise from said holders as they pass around said feeding mechanism.
10. In a phonograph, a record rotating table rotatable on a vertical axis, means for rotating the same throughout the operation of the phonograph, means for supplying successive records of the same or different sizes thereto while said table is rotating, reproducer mechanism operative on records on said table and movable on vertical and horizontal axes, and means independent of the records controlling said reproducer and operative to actuate the latter to reproduce automatically successive records of the same or different sizes.
11. In a phonograph, a record rotating table rotatable on a fixed vertical axis, a movable reproducer mechanism cooperating with records on said table, record feeding mechanism having a plurality of spaced holders receiving records of different diameter in different predetermined positions and means for delivering the records carried thereby successively on said table actuating said holders to deliver records directly on said table, record discharging mechanism operative to discharge records on said table, and means for operating said mechanisms successively to feed, reproduce and discharge records of different diameter.
12. In a phonograph, record magazine means for receiving a series of records, a record rotating table, record reproducing means for reproducing records on said table, means for moving the record receiving means and the series of records therein toward the table axis in each feeding operation and disposing one end record in said series in substantially centered position over said table, and means for thereupon effecting lateral movement of said end record to separate it from said magazine and permit centering of said record upon said table.
13. In a phonograph, record magazine means for receiving a series of records, a record rotating table, record reproducing means for reproducing records on said table, and means for moving the record receiving means and the series of records therein toward the table axis in each feeding operation successively moving each adjacent end record into a position substantially at right angles to the position in which it was received in the magazine while the remaining records in the series are disposed in said magazine means at one side of said table.
14. In a phonograph, record magazine means for receiving a series of records, a record rotating table, record reproducing means for reproducing records on said table, and means for moving the record receiving means and the series of records therein toward the table axis in each feeding operation and feeding one end record in said series

into centered position on the table including means engaged by the record to be centered as the series moves relative to the table for separating said record from said magazine means and disposing it in centered position relative to the table.

95. In a phonograph, record magazine means for receiving a series of records, a record rotating table, record reproducing means for reproducing records on said table, and means for moving the record receiving means and the series of records therein toward the table axis in each feeding operation and feeding one end record in said series into centered position on the table while the other records in said series remain in said magazine means at one side of said table, said magazine means receiving the records substantially in upright position therein and supporting the records remaining to be played in substantially upright position during reproduction of each centered record.

96. In a phonograph, a record rotating table, an endless conveyor in alignment therewith feeding records toward said table, and means operative at the end of said conveyor adjacent said table for tilting a record on said conveyor into centered position on said table.

97. In a phonograph, a record rotating table rotatable on a vertical axis during reproduction, a record feeding magazine having means for carrying a series of records in alignment with said table and in substantially upright position with the records removable laterally relative to the axis of other records therein and successively feeding end records therein toward the table axis ready for centering on said table, mechanism including swinging means movable about pivot means extending transversely relative to said axis and successively acting on end records presented by said magazine for effecting centering of said records on said table while the latter rotates and while the other records in the magazine remain in substantially upright position, and means for successively reproducing said centered records.

98. A phonograph having a record rotating table rotatable on a vertical axis during reproduction, means for rotating the same throughout the operation of the phonograph, a record feeding magazine having means carrying a series of records in alignment with said table and in substantially upright position with the records freely removable laterally relative to the axes of other records therein and feeding end records therein toward the table axis ready for centering on said table, means for successively automatically reproducing records fed by said feeding means engaging successive records for reproduction while said records are in horizontal position on said table, and mechanism including swinging means movable about pivot means extending transversely relative to the table axis and acting on reproduced records on the table and on end records successively presented by said magazine for substantially simultaneously discharging a reproduced record from said table and centering a new record on said table while the latter is rotating.

99. In a phonograph, a record rotating means rotatable on a vertical axis, and mechanism for delivering a record in horizontal and centered position on said means while the latter is rotating on said axis including record delivery means from which the record is adapted to be extracted by a horizontal movement of the record, and means carried on said record rotating means for im-

- parting a horizontal movement to the record to separate the same from said delivery means and dispose the record in centered position.
100. In a phonograph, a record rotating table 5 rotatable on a vertical axis, an axial record centering pin upstanding from the table, and means for feeding records laterally over said pin and into a centered position thereon in which said pin is received in the central aperture in the record, said means including a record supporting member having a recess in which said record is supported and from which it is freely removable at any time during feeding, and means for releasing the record from its support entirely by its 10 contact with the centering pin, said pin having means above its record centering portion for imparting a horizontal movement to extract the record from said recess prior to the deposit of the record on the table.
101. In a phonograph, a record rotating means 20 rotatable on a vertical axis, and mechanism for delivering a record in horizontal and centered position on said means including record delivery means, including a record holder from which the record is freely removable at any time during delivery, for disposing the record in substantially horizontal position above said record rotating means slightly offset with respect to the axis thereof, and means for releasing the record from 25 said holder entirely by its engagement with said record rotating means including means carried on said record rotating means and engageable with the record only when the latter is disposed in substantially centered position with respect there- 30 to by said record delivery means for imparting a horizontal movement to the record to center the same on said record rotating means while separating the record from the record holder of 35 said delivery means.
102. In a phonograph, a record rotating means 40 rotatable on a vertical axis, and mechanism for delivering an axially apertured record in horizontal and centered position on said means including record delivery means for disposing the record in substantially horizontal position above said record rotating means slightly offset with respect to the axis thereof, and means carried on 45 said record rotating means and engageable with the record only when the latter is disposed in substantially centered position with respect thereto by said record delivery means for imparting a horizontal movement to the record to center the same on said record rotating means while 50 separating the record from said delivery means, including a record centering pin engageable with the edge of the axial aperture in the record.
103. In a phonograph, a record magazine having 55 means extraneous of the record apertures for receiving and disposing axially apertured records in substantially upright and parallel position therein, a record rotating table in alignment with said records beyond one end of said magazine and rotatable on a vertical axis during reproduction and having an upstanding axial centering pin, 60 means for successively presenting records in said magazine in position for centering on said table, and swinging means for centering records on said table effecting relative movement between the presented record and the table while the latter rotates and limiting said relative movement by bringing the edge of the record aperture and said pin into engagement prior to engagement of the record with the table and prior to locating the record in playing position on the table.
104. In a phonograph, a record magazine, a

laterally offset table rotatable on a vertical axis and having an upstanding axial centering pin, means for rotating said table throughout the operation of the phonograph, means for moving said magazine to present a record therein for centering, swinging means engageable with the opposite sides of the edge of a presented record in said magazine for moving the same laterally and between said magazine and table substantially into centered position on the latter, and means for 10 effecting release of the record edge by said edge engaging means while the record aperture is in substantial registry with said pin, both said last mentioned means being operative while said table is rotating.

105. In a phonograph, a record magazine, a laterally offset table rotatable on a vertical axis and having an upstanding axial centering pin, means for rotating said table throughout the operation of the phonograph, means for moving said 20 magazine to present a record therein for centering, mechanism operative while said table is rotating including swinging means engageable with the opposite sides of the edge of a presented record in said magazine for moving the same laterally and between said magazine and table substantially into centered position on the latter, means for effecting release of the record edge by said edge engaging means while the record aperture is in substantial registry with said pin, and 30 means for enabling mixed records of different diameter to be fed by said swinging means in any order from said magazine to said table.

106. In a phonograph, a record magazine having means extraneous of the records for disposing 35 records therein in substantially upright position, a record rotating table rotatable on a vertical axis and in alignment with said magazine and laterally spaced from the lowermost edges of the records in said magazine, said table having an unobstructed space above the same, and mechanism for successively disposing the adjacent end records in said magazine in centered position on said 40 table including means for moving all of the records in said magazine bodily toward the table axis and moving said adjacent end record through said 45 unobstructed space across the table axis into spaced relation to said table above the same and means for thereupon effecting a lateral movement of said record into centered position on said 50 table to separate the same from said magazine and center said record.

107. In a phonograph, a record rotating table, a record magazine, automatic reproducer mechanism including a swinging reproducer also movable below the plane of said table when no record is thereon, and mechanism for feeding successive records in said magazine on to said table and discharging the reproduced records therefrom, including a power train, a clutch controlling the 60 connection of said train to said feeding and discharging mechanism having a member biased to clutch engaging position and rotatable with said train, and means operated by said reproducer mechanism upon the reproduction of a record for 65 releasing said member to connect said power train and effect rotation of said member and for engaging said member to disconnect said power train after a revolution of said member, and means operative when said reproducer moves below said 70 plane for preventing disconnection of said power train.

108. In a phonograph, a record rotating table rotatable on a vertical axis and having upstanding axial centering means, a record magazine 75

- 5 laterally offset with respect to said table and disposed constantly in the same horizontal planes and having separate record receptacles for carrying a series of records in substantially parallel relation, reproducer mechanism including an oscillating reproducer co-operating with records on said table in the same position of the latter for all records, and mechanism for depositing records in said receptacles in centered position on 10 said table including swinging means for swinging each record while in its receptacle into spaced relation above said table and means for thereupon transferring the record in said receptacle into playing position on said table.
- 15 109. In a phonograph, a record rotating table rotatable on a vertical axis, power means for rotating said table throughout the operation of the phonograph, a record magazine laterally offset with respect to said table and disposed constantly in the same horizontal planes and having parallel record receptacles for separately supporting a plurality of records in substantially upright position, reproducer mechanism including a swinging reproducer cooperating with records on 20 said table in the same position of the latter for all records, and mechanism for successively depositing records in said receptacles in centered position on the table including swinging means for swinging substantially upright records success- 25 sively into horizontal playing position on said table.
- 30 110. In a phonograph, a record rotating table rotatable on a fixed vertical axis, power means for rotating said table throughout the operation of the phonograph, a record magazine disposed constantly in the same horizontal planes at one side of said table and having parallel record receptacles for separately supporting a plurality of records in substantially upright position, re- 35 producer mechanism including a swinging re- producer cooperating with records on said table in the same position of the latter for all records, and mechanism for successively disposing records in said receptacles in centered position on the 40 table including swinging means swinging sub- stantially upright records successively into horizontal playing position on said rotating table, said magazine, feeding mechanism and table having the axes of the records thereon disposed sub- 45 stantially in alignment.
- 50 111. In a phonograph, a record rotating table rotatable on a vertical axis and having upstanding axial centering means, a record magazine laterally offset with respect to said table and disposed constantly in the same horizontal planes and having separate record receptacles for carrying a series of records in substantially parallel relation, reproducer mechanism including an oscillating reproducer cooperating with records on said table, 55 mechanism for depositing records in said receptacles in centered position on said table including swinging means for swinging each record while in its receptacle into spaced relation above said table, and means for thereupon transferring the record in said receptacle into playing position on said table, and means for effecting relative movement between the reproduced record and the table to discharge the reproduced record.
- 60 112. In a phonograph, a record rotating table rotatable on a vertical axis, a record magazine having an endless conveyor in alignment with said table extending beneath the records in said magazine and turning relatively angularly at a point adjacent said table, and mechanism for successively delivering records in said magazine

6 on to said table and reproducing the same thereon including means for successively actuating said conveyor, means for depositing an end record in said magazine in centered position on said table and successively presenting another record in said end position, and means for successively reproducing said records as they are deposited on said table.

7 113. In a phonograph, a record rotating table rotatable on a vertical axis during reproduction, 10 a magazine for records of different diameter and including an endless conveyor disposed in substantial alignment with said table, and mechanism for automatically successively delivering records of the same or different diameter from 15 said magazine into centered position on said table and reproducing the same thereon including means for actuating said conveyor and successively presenting records in a substantially upright position at one end of said magazine, swing- 20 ing means for successively effecting relative movement between said presented records and said table swinging the records into centered playing position, and means for successively reproducing the records in the latter position.

25 114. In a phonograph, a record rotating table rotatable on a vertical axis during reproduction, 30 a magazine including an endless conveyor disposed in alignment with said table and also having means for supporting the records in substantially upright position while enabling free removal of the records laterally relative to the axes of other records therein, and mechanism for automatically successively delivering records from said magazine into centered position on said table 35 and reproducing the same thereon including means for successively actuating said conveyor to present records for centering in a substantially upright position at one end of said magazine, swinging means for successively effecting relative movement between the records in said presented position and said table and bringing the records into centered playing position, and means for successively reproducing the records when disposed in said playing position.

40 115. In a phonograph, a record rotating table, a movable reproducer mechanism cooperating therewith, an endless conveyor mechanism carrying records and delivering them in horizontal position on the table while the latter is rotating, 50 record discharging mechanism also operative while said table is rotating, and means for operating said mechanisms to reproduce a series of records.

45 116. In a phonograph, mechanism for automatically reproducing a series of records having a manually adjustable longitudinally movable indicator movable manually longitudinally in opposite directions and automatically adjustable in one direction by said mechanism, and a motor 60 driving mechanism for said first mentioned mechanism having a switch automatically operable by said indicator upon a continuation of the longitudinal movement in one direction.

55 117. In a phonograph, mechanism operative to 65 reproduce a series of records having longitudinally moving record feeding mechanism and controlling mechanism therefor, the latter having a longitudinally adjustable control member movable with said feeding mechanism or independently relative thereto.

70 118. In a phonograph, a horizontal record rotating table, means engageable with the bottom edges of the records and supporting records in upright positions at one side of said table. a 75

record receptacle at one side of said table, and means for successively feeding said records onto said table, reproducing the same, and discharging them into said receptacle.

5 119. In a phonograph, a horizontal record rotating table rotatable on a fixed axis, means for rotating said table throughout the operation of the phonograph, means for supporting records of different predetermined sizes in substantially upright position at one side of said table, and means automatically operative regardless of said variation in the size of the records for successively feeding said records on to said table and reproducing the same thereon.

15 120. In a phonograph, a horizontal record rotating table, means for supporting records of different predetermined sizes in upright positions at one side of said table, a record receptacle at one side of said table, and means automatically operative regardless of said predetermined variation in the size of the records for successively feeding said records onto said table, reproducing the same, and discharging them into said receptacle.

20 121. In a phonograph, record rotating means having upstanding record centering means thereon, means for rotating said record rotating means about a stationary axis throughout the operation of the phonograph, and record feeding mechanism having swinging means swinging about a stationary axis disposed angularly to said stationary axis for feeding automatically into centered position on said rotating means, while said rotating means is rotating about said stationary axis, successive records of the same diameter or of different predetermined diameters.

25 122. In a phonograph, record rotating means rotatable about a stationary axis, means for rotating said means throughout the operation of the phonograph, record feeding mechanism for feeding automatically into centered position thereon while said means is rotating, successive records of the same diameter or of different predetermined diameters, means for successively automatically reproducing said records on said rotating means, record discharging means movable relative to said feeding mechanism likewise operative while said rotating means is rotating for automatically discharging said records of different diameters as they are successively reproduced, said feeding mechanism having means for moving a new record over said record rotating means into adjacency thereto during record discharge and said discharging means discharging a record while maintaining the same out of conflict with said new record.

30 123. In a phonograph, record rotating means, means for rotating the same throughout the operation of the phonograph, record feeding mechanism for automatically feeding thereto while said means is rotating, successive records of the same diameter or of different predetermined diameters, and reproducer mechanism automatically adjustable independently of the records fed to reproduce records of the same or different diameter as they are fed to said rotating means.

35 124. In a phonograph, record rotating means, means for rotating the same throughout the operation of the phonograph, record feeding means for automatically delivering thereon successive records of the same or different diameter while said first mentioned means is rotating, reproducer mechanism, and automatic means for adapting the latter to cooperate with delivered

records of different diameter including a member moving with said feeding mechanism and controlling means intermittently actuated by said member.

40 125. In a phonograph, record rotating means, a swinging reproducer, record feeding means, mechanism for raising and lowering said reproducer relative to a record, and a driving connection for said feeding mechanism movable with said raising and lowering mechanism and having means for interrupting the drive of said feeding mechanism during swinging movement of said reproducer.

45 126. In a phonograph, a record rotating table movable on a single axis, means for rotating said table throughout the operation of the phonograph, automatic record feeding means supporting records in substantially upright position and swinging them into horizontal centered position on said table, automatic reproducing mechanism acting on records on said table, and means for discharging records from said table while said record feeding means is lowering a new record over the table.

50 127. In a phonograph, a record rotating table movable on a single axis, means for rotating said table throughout the operation of the phonograph, automatic record feeding means receiving records in substantially upright position and delivering them in horizontal position on the table, automatic reproducer mechanism acting on records on said table, a receptacle adapted to receive reproduced records discharged from said table, and automatic record discharging means discharging reproduced records from the table into said receptacle.

55 128. In a phonograph, a record rotating table movable on a single axis, automatic record feeding means having a series of individual record supports supporting records in substantially upright position and delivering them in horizontal position on the table, automatic reproducer mechanism acting on records on said table, a receptacle below the table, and automatic record discharging means movable independently of the table and discharging records from the table into said receptacle.

60 129. In a phonograph, a record rotating table rotatable about a single vertical axis, feeding mechanism receiving records in upright position therein and having means for automatically delivering successive records of different diameter in horizontal position on said table while the latter rotates, mechanism for automatically reproducing successive records on said table, and record removing means other than said feeding means and below a record on said table during reproduction for successively automatically removing the reproduced records while said table rotates.

65 130. In a phonograph, a record rotating table rotatable on a single fixed axis, means for rotating said table throughout the operation of the phonograph, automatic record feeding means receiving records in substantially upright position in alignment with said table and successively delivering them in horizontal position on the table, automatic reproducer mechanism acting on the records when delivered on said table, and automatic record discharging means successively discharging reproduced records from the table, said feeding mechanism including a magazine having said records received in the latter in substantially upright position and disposed in upright position therein during reproduction.

and having any record in said magazine changeable at will during the reproduction of any previously fed record while continuing reproduction.

131. In a phonograph, a record rotating table 5 rotatable on a single fixed axis, means for rotating said table throughout the operation of the phonograph, automatic record feeding means receiving records in substantially upright position in alignment with said table and successively 10 delivering them in horizontal position on the table, automatic reproducer mechanism acting on the records when delivered on said table, automatic record discharging means successively 15 discharging reproduced records from the table, and means for adapting the phonograph for automatic operation on successive records of the same or different diameter arranged in any order in said feeding mechanism.

132. In a phonograph, a record rotating table, 20 record feeding mechanism having an endless conveyor adapted to feed mixed records of different diameter one by one, directly on said table, and automatic adjustable reproducer mechanism acting on said records on said table and automatically 25 operative in step with said feeding mechanism.

133. In a phonograph, a record rotating table, reproducer mechanism adjustable to reproduce records of different diameter fed to said table, 30 record feeding mechanism having an endless conveyor adapted to feed mixed records of different diameter one by one directly on said table, and mechanism operatively connected between said mechanisms controlled by said feeding mechanism and controlling the adjustment of said 35 reproducing mechanism.

134. In a phonograph, a record rotating table, automatic reproducer mechanism adjustable to reproduce records of different diameter one by 40 one on said table, and record feeding mechanism having an endless conveyor adapted to center on said table one by one records of different diameter in any predetermined sequence and in operation automatically adjust said reproducer mechanism for operation on the fed records.

135. In a phonograph, adjustable operatively 45 connected reproducer and record feeding mechanisms for automatically feeding and reproducing successively records of different diameter in a predetermined sequence and having a record 50 rotating table and record receiving means receiving records of different diameter in different positions and delivering them directly in centered position on said table, said reproducer mechanism being automatically adjustable by said feeding mechanism and operative thereby successively to reproduce automatically either records of the same diameter or records of different diameters in different predetermined sequences, depending upon the location of the 55 records in said receiving means.

136. In a phonograph, a record rotating table 60 having upstanding axial centering means, means for rotating said table throughout the operation of the phonograph, record receiving means permitting edgewise withdrawal of any record therein, feeding mechanism for automatically feeding successive records of different diameter projecting said records laterally across the table axis 65 into centered position on said table, swinging reproducer mechanism automatically operative on a record of a predetermined size on said table, and means for automatically adjusting the range 70 of swing of said reproducer mechanism to ac-

cord with the size of the record delivered by said feeding mechanism.

137. In a phonograph, a record rotating table 5 rotatable on a vertical axis, and record delivery mechanism delivering records successively on 10 to said table and having a horizontally disposed endless conveyor disposed at one side of said table and successively feeding records into centered position on said table beyond the end of said conveyor. 10

138. In a phonograph, a record rotating table 15 rotatable on a vertical axis and having axial centering means, and mechanism for supplying successive records thereto having a horizontally 20 disposed endless conveyor disposed at one side of said table and co-operating centering means co-operating with said conveyor and successively centering the records on said centering means. 15

139. In a phonograph, a record rotating table 25 rotatable on a vertical axis, record delivery mechanism having an endless conveyor at one side of 30 said table delivering records directly over said table and co-operating means for successively centering on said table successive records so delivered by said conveyor, means for successively 35 automatically reproducing said records on said table, and means for successively automatically removing the reproduced records on said table. 20

140. In a phonograph, a record rotating table 35 rotatable on a vertical axis, record delivery mechanism having a horizontal endless conveyor at one side of said table and co-operating record centering means co-operating with said conveyor and successively centering the records on said table, reproducer mechanism operative in 40 timed relation with said delivery mechanism, and record discharging means under the records on said table during reproduction and movable upward to discharge the reproduced records. 35

141. In a phonograph, a magazine having 45 means for supporting a plurality of records of different predetermined diameters with an end record normally disposed in a position ready for transverse movement relative to the axes of the other records therein, a laterally offset record 50 rotating table rotatable on a vertical axis and having upstanding record centering means thereon, supporting means for said table disposing said axis in vertical playing position throughout the operation of the phonograph, means for 55 rotating said table throughout the operation of the phonograph, means for automatically feeding successive end records of different diameter transversely from their position in said magazine and into centered position on said table 60 while the latter rotates in playing position, and mechanism for successively automatically reproducing said records on said table. 55

142. In a phonograph, a record rotating table 65 rotatable on a vertical axis, means carrying a plurality of records to be reproduced on said table, and mechanism for successively centering records carried by said means on said table while the latter rotates in playing position comprising means for bodily moving said record carrying 70 means transversely relative to the table axis toward centered position on said table and co-operating record centering means engageable with successive records moved with said record carrying means and successively centering said 75 records on said table. 60

143. In a phonograph, a record rotating table 75 rotatable on a vertical axis, means carrying a plurality of records to be reproduced on said table, and mechanism for successively centering

records carried by said means on said table while the latter rotates in playing position comprising means for bodily moving said record carrying means transversely relative to the table axis and 5 co-operating record centering means engageable with successive records moved with said record carrying means and successively centering said records on said table, said co-operating means being immovable laterally relative to said record

10 carrying means and upon continued movement of the latter disengaging a record therefrom.

144. In a phonograph, a record rotating table rotatable on a vertical axis, means carrying a plurality of records of different predetermined 15 diameters to be reproduced on said table, and mechanism for successively centering records of different diameter carried by said means on said table while the latter rotates in playing position comprising means for bodily moving said record carrying 20 means transversely relative to the table axis toward centered position on said table and co-operating record centering means engageable with successive records moved with said record carrying means and successively centering said 25 records on said table.

145. In a phonograph, a record rotating table rotatable on a vertical axis, means carrying a plurality of records to be reproduced on said table, mechanism for successively centering records 30 carried by said means on said table while the latter rotates in playing position comprising means for bodily moving said record carrying means transversely relative to the table axis toward centered position on said table and co-operating record centering means engageable with successive records moved with said record carrying means and successively centering said records on said table, reproducing mechanism for successively reproducing the centered records, and mechanism for successively removing the 35 reproduced records from said table having means disposable under the successive records thereon upon reproduction and means for effecting a relative movement between the same and said table to remove a record from the latter.

146. In a phonograph, a record rotating table, reproducer mechanism including a swinging reproducer, a cam having a peripheral gap therein, a member engageable with the periphery of said cam while the cam rotates and movable into said gap, means for rotating said cam rotating the same following the reproduction of a record, and means controlled by said member for effecting movement of said reproducer from record 40 reproduced position into initial playing position, said member being in contact with said cam only during the aforesaid movement of said reproducer and wholly out of contact with the limits of said gap during record reproduction, and means for discharging a record from said table following reproduction and presenting a new record for reproduction while said member is in contact with said cam.

147. In a phonograph, a record rotating table 45 rotatable constantly in the same planes, reproducer mechanism including a swinging reproducer, a cam having a peripheral gap therein, a member engageable with the periphery of said cam while the cam rotates and movable into said gap, means for rotating said cam rotating the same upon completion of the reproduction of a record, means controlled by said member for effecting movement of said reproducer from record reproduced position into initial playing position, said 50 member being in contact with said cam during

the aforesaid movement of said reproducer and wholly out of contact with the limits of said gap during record reproduction, tripping means responsive to the movement of said reproducer following reproduction of a record for effecting reproducer operating engagement of said member and cam, and means for adapting said mechanism to reproduce records of a different diameter. 5

148. In a phonograph, a record rotating table, 10 a swinging reproducer adapted to traverse the playing groove of a record on said table and thereafter to be returned automatically to its initial playing position relative to said table, power operated means for rotating said table 15 in the same planes throughout the operation of the phonograph, reproducer controlling mechanism for effecting the aforesaid automatic return movement of said reproducer following reproduction of a record including a cam member having 20 a peripheral cam face formed with a gap in its periphery, said cam member being rotatable by said power operated means at least during the automatic return movement of said reproducer, and a reproducer actuating member adapted to 25 enter said gap into a position to engage said cam face and control said reproducer upon rotation of said cam member, tripping means for effecting the aforesaid engagement of said cam and actuating member including a latch member actuated by said reproducer mechanism following the reproduction of a record by said reproducer, and means for discharging a record as it is reproduced and presenting a new record for engagement by said reproducer in the initial play- 30 ing position thereof. 35

149. In a phonograph, a record rotating table, reproducer mechanism including a swinging reproducer operable upon a record on said table, a cam comprising a plurality of cam surfaces and 40 having a peripheral gap therein, means rotating the cam as a unit following reproduction of a record for swinging said reproducer from record reproduced position into initial playing position on a new record, a member engageable with the periphery of said cam while the cam rotates and movable into said gap, said member being in contact with said cam only during the aforesaid movement of said reproducer and wholly out of contact with the limits of said gap during record 45 reproduction, and means for discharging a record as it is reproduced and presenting a new record in the path of said reproducer as the latter moves into initial playing position. 50

150. In a phonograph, a record rotating table, 55 a swinging reproducer adapted to traverse the playing groove of a record on said table and thereafter to be returned automatically to its initial playing position relative to said table, reproducer controlling mechanism for effecting 60 the aforesaid automatic return movement of said reproducer following reproduction of a record including a cam member rotatable by power means at least during the return movement of said reproducer and also a reproducer actuating 65 member engaging said cam during said return movement, power operated means for rotating said table in the same planes throughout the operation of the phonograph and connectible at will to actuate said cam and actuating member, 70 means tripped by the movement of said reproducer following record reproduction and controlling the connection of said power means to said actuating member to return said reproducer, and means for discharging each record as it is 75

reproduced and presenting substantially simultaneously with the discharge thereof a new record in the path of movement of said reproducer into its initial playing position.

5 151. In a phonograph, a record rotating table, reproducer mechanism including a swinging reproducer, a cam having a peripheral gap therein, a member engageable with the periphery of said cam while the cam rotates and movable into 10 said gap, means for rotating said cam following the reproduction of a record, and means controlled by said member for effecting movement of said reproducer from record reproduced position into initial playing position, said member 15 being in contact with said cam only during the aforesaid movement of said reproducer and wholly out of contact with the limits of said gap during record reproduction, means for discharging a record from said table upon reproduction 20 and placing said reproducer on a new record, and means for adapting the phonograph to reproduce records of a different diameter.

152. In a phonograph, a record rotating table, reproducer mechanism including a swinging reproducer, a cam having a peripheral gap therein, a member engageable with the periphery of said cam while the cam rotates and movable into said gap, means for rotating said cam following the reproduction of a record, means controlled 30 by said member for effecting movement of said reproducer from record reproduced position into initial playing position, said member being in contact with said cam only during the aforesaid movement of said reproducer and wholly 35 out of contact with the limits of said gap during record reproduction, and means for automatically controlling the phonograph to reproduce automatically successive records of the same or different diameters.

40 153. A phonograph having a record rotating table rotatable on a fixed axis, mechanism including a swinging reproducer for successively automatically reproducing standard records and engaging successive records for reproduction 45 while said records are on said table, mechanism operative while said table is rotating including means for swinging said reproducer away from a reproduced record, and also including a swinging record engaging discharging member movable to effect discharge of said reproduced record, and having means for discharging a reproduced record from said table upon reproduction and substantially simultaneously presenting in the path of said reproducer a new record for 50 reproduction by the latter and for also actuating substantially simultaneously both said swinging reproducer and said swinging record engaging discharging member to return to cooperate with the new record, and means for adapting the 55 phonograph for like automatic operation on a record of another diameter.

154. A phonograph having a record rotating table rotatable in fixed planes on a fixed axis, mechanism including a swinging reproducer for 60 successively automatically reproducing standard records and engaging successive records for reproduction while said records are on said table and the latter is rotating, and mechanism operative in response to movement of the swinging 65 reproducer while said table is rotating including a swinging record engaging discharging member, said mechanisms having means for

effecting discharge of a reproduced record from said table upon reproduction and presenting in the path of said reproducer a new record for reproduction by the latter and for also actuating both said swinging reproducer and said swinging record engaging discharging member to return to cooperate with the new record, and said last mentioned means including controlling cam means substantially simultaneously swinging both said swinging reproducer and said swinging record engaging discharging member relative to the reproduced record upon reproduction thereof and subsequently actuating substantially simultaneously both to return to positions to cooperate with the new record.

155. In a phonograph, a magazine having means extraneous of the record apertures for simultaneously supporting a plurality of records of the same or different diameter while enabling successive records to be fed transversely therefrom, a laterally offset record rotating table rotatable on a vertical axis and having upstanding axial record centering means thereon, supporting means for said table disposing said axis in vertical playing position throughout the operation of the phonograph, means for rotating said table about said axis throughout said operation, means for automatically feeding successive records of the same or different diameter transversely from their position in said magazine and 20 relative to the axes of other records therein and into centered position on said table while the latter rotates in playing position, and mechanism for successively automatically reproducing said records on said table irrespective of their 25 variations in diameter.

156. In a phonograph, a magazine having means for simultaneously supporting a plurality of axially apertured records of the same or different diameter, a laterally offset record rotating table rotatable on a vertical axis and having axial record centering means thereon upstanding from said table, supporting means for said table disposing said axis in vertical playing position throughout the operation of the phonograph, means for rotating said table about said axis throughout said operation, means for automatically feeding successive records of the same or different diameter from said magazine into centered position on said table while maintaining 40 the aperture in each record in vertical alignment with said upstanding centering means and feeding the records as they pass out of said magazine continuously in the direction of said centering means, and mechanism for successively automatically reproducing said records on said table 45 irrespective of their variations in diameter.

157. In a phonograph, a horizontal record rotating table rotatable on a fixed axis in fixed horizontal planes, means for rotating said table throughout the operation of the phonograph, means extraneous of the record apertures for supporting mixed records of different diameters in substantially upright position at one side of said table, and feeding and reproducing mechanism automatically operative regardless of variation in the diameter of the records and having means extraneous of the record apertures for successively feeding said records on to said table 60 and means for successively reproducing the same 65 thereon.

CLEMMA R. RANEY.

CERTIFICATE OF CORRECTION.

Patent No. 2,029,190.

January 28, 1936.

CLEMMA R. RANEY.

It is hereby certified that error appears in the printed specification of the above numbered patent requiring correction as follows: Page 4, first column, line 71, for "springs" read spring; and second column, line 10, strike out the word "in"; page 9 second column, line 11, claim 18, after "table" insert a comma; page 10, first column, line 56, claim 32, strike out the article "a" second occurrence; page 17, second column, line 41, claim 106, for "spaced" read space; page 22, first column, line 59, claim 153, for "drecord read record; and second column, line 13, claim 154, strike out the word "actuating" and insert the same before "both" in line 14 of said claim; and that the said Letters Patent should be read with these corrections therein that the same may conform to the record of the case in the Patent Office.

Signed and sealed this 21st day of July, A. D. 1936.

Henry Van Arsdale

(Seal)

Acting Commissioner of Patents.

DISCLAIMER

2,029,190.—*Clemma R. Raney, Riverside, Ill. PHONOGRAPH. Patent dated January 28, 1936. Disclaimer filed October 12, 1939, by the patentee.*
Hereby enters this disclaimer to claims 141 and 155 of said Letters Patent.
